UNITED STATES PATENT OFFICE

JOHN H. VOSS, OF BERWYN, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed May 11, 1931. Serial No. 536,342.

This invention relates to telephone systems in general, but is concerned more particularly with small systems of the type commonly known as private automatic exchanges.

5 Private automatic exchanges are as a rule privately owned by individuals or corporations and are installed in factories or other establishments for providing local service between a small number of local telephone lines 10 and for establishing connections over trunk lines to the main office of the telephone company's network.

It has been customary, heretofore, in systems of this type to provide an attendant operator or some special line for completing all outgoing and incoming calls between the private automatic exchange and the main telephone office. Accordingly, one of the objects of the invention is to do away with the 20 attendant operator's position or special line and to provide means for enabling any one of a number of local subscribers' lines to extend and complete outgoing calls or answer any incoming call between the private automatic 25 exchange and the main telephone office.

Another object of the invention is the provision of means for enabling a local subscriber, after answering an incoming trunk call, to hold this trunk line and complete a 30 call to the subscriber desired by the incoming call from the same telephone set over the local switchtrain. When the desired subscriber is informed of the call, such subscriber will cause the trunk call to be connected to his line, whereupon the first local 35 subscriber is informed of such transfer and releases from the connection.

A further object of the invention is to provide holding means whereby one trunk connection can be held while the local subscriber 40 receives a local call, makes a local call, makes an outgoing trunk call, or answers an incoming trunk call over the same telephone set. The local subscriber may, if desired, hold 45 both trunk calls and return to each as desired or may transfer one of the trunk calls to another local subscriber.

A still further object of the invention is to provide guarding means for held trunk lines 50 and for enabling only a certain subscriber to

be connected thereto when the trunk line is to be transferred to such subscriber's line.

One of the features of the invention resides in the circuit arrangements whereby it is not necessary for a subscriber in making an outgoing trunk call or in answering an incoming trunk call to know which trunk to connect with. That is, a subscriber always operates the same key in accepting a transferred or answering an incoming trunk call on any 55 trunk line and always operates the same outgoing key to make outgoing trunk calls regardless of the number of trunks available for such calls. This simplicity of operation on the part of the subscribers is considered 60 advantageous over the existing similar systems because of the uniform operation performed by the subscriber.

Other features relating to signalling, supervision, code and conference calling and restricted service, are mainly improved circuit details and will, together with the ones named above, be explained hereinafter, reference being had to the accompanying drawings which comprise Figs. 1 to 8, inclusive, 70 and which show by means of the usual circuit diagrams a sufficient amount of apparatus to enable the invention to be described and understood.

Fig. 1 illustrates two local subscribers' lines 80 S and S' in which the line S can make and receive local calls only, while the line S' can make and receive trunk calls, can transfer trunk calls and can hold trunk calls while making or receiving local calls.

Fig. 2 illustrates a local subscriber's line S² which can make and receive both local and trunk calls, can transfer trunk calls to other local lines, and can hold trunk calls while making, answering, or transferring other 85 trunk calls.

Fig. 3 illustrates the wipers and relays of a finder in one of the finder-connector links.

Fig. 4 illustrates the wipers and relays of the connector in the corresponding finder-connector link.

Fig. 5 illustrates a code-call finder switch.

Fig. 6 at TSS illustrates the transfer sequence switch, at BTR illustrates the busy-tone relays, at RIR illustrates the ring-in- 100

terrupter relays, and at ASR illustrates the alarm-signalling relays.

Figs. 7 and 8 illustrate the wipers of the trunk finder and relays of a two-way trunk circuit which is one of a number of trunk circuits connecting the local automatic exchange to a telephone exchange of the telephone company's network.

Referring now to Figs. 1 and 2 in detail, all subscribers, such as S, S', and S², are equipped with a standard and well-known monophone telephone set. Each set comprises a handset T and R, a calling device CD, a cradle and cradle spring CS, an induction coil IC, and the ringer bells RB. Each line has a local line circuit, the conductors of which terminate in the local finder and connector banks for completing local calls. Each local line circuit has a two-step cut-off relay and a line relay, such as relays 7, 117, and 217, which is common to a group of lines. Attached to the base of each standard monophone set of subscribers' lines, such as S' and S², is a sub-base, such as SB shown in the dotted rectangle, having a number of spring assemblies and keys for operating the same when making or receiving trunk calls. The sub-base of the subscribers' lines, such as S', have only two keys, an "OUT" key for initiating outgoing trunk calls, and an "ANS" key for answering incoming trunk calls; while the sub-base of subscribers' lines, such as S², have an additional or "HOLD" key. A push-button is also provided in the sub-base for flashing an operator in a trunk call to a manual exchange or for cancelling the digits dialled if an error has been made in dialling an automatic subscriber in either the local or a distant automatic exchange. Conductors extending from the spring assemblies controlled by these keys, extend to the trunk-line circuits and from there terminate in the banks of the trunk finder. The trunk-line circuits of subscribers' lines, such as S', comprise an individual two-step cut-off relay and an individual relay for selecting one of two common line relays depending upon whether the "OUT" or "ANS" key is operated. The trunk-line circuits of subscribers' lines, such as S², are similar to trunk-line circuits of the S' subscribers, and, in addition, have an individual holding circuit comprising four relays, one of which is also a two-step cut-off relay. The trunk-line circuits of S² subscribers terminate in the banks of a trunk finder in the same manner as the S' subscribers trunk-line circuits, and, in addition, terminate in an additional set of bank contacts in the trunk finder for enabling the subscribers' lines, such as S², to hold one trunk connection while talking over another. The local line circuits of the S² subscribers' lines also terminate in two places in the local finder banks for enabling such subscribers to transfer a second trunk call to another

local subscriber, while the first trunk call is being held. All the subscribers' lines also terminate in the finder banks of the code call switch shown in Fig. 5.

The mechanical construction of the spring assemblies and keys in the sub-bases, diagrammatically illustrated in Figs. 1 and 2, are being shown and claimed in a co-pending application of H. F. Obergfell, Serial No. 586424, filed May 11, 1931. Since the sub-bases of the subscribers' lines, such as S' and S², are somewhat similar, the key and spring assemblies in the sub-base of Fig. 2 only will be described. When the hand telephone set is removed from the cradle, springs 253 automatically open and springs 254 automatically close. If either the "OUT" key or the "ANS" key is depressed, the bar 261 slides in a horizontal direction, and by means of bushings 262, 263, and 264, operate springs 251, 252, 256, 257, and 258. Springs 255 are operated only when the "ANS" key is depressed. A mechanical lock (not shown) is provided for preventing either the "OUT" or "ANS" key, from being operated when the other is operated. The catch bar 260 is operated responsive to the removal of the handset from the cradle to position itself so that when springs 252 and 255 are operated, the same will be mechanically locked until the handset is replaced on the cradle irrespective of the subsequent operations of the keys. The "HOLD" key controls only springs 259. The three keys "ANS", "OUT", and "HOLD" are keys or levers which are moved off center and remain in such positions until moved by hand back to normal or until the handset is replaced on the cradle which automatically returns the keys to their normal positions. The push-button PB, controlling springs 250 is of the self-restoring type and operates the springs 250 only as long as the push-button is depressed.

The finder switches, one of which is shown in Fig. 3, are mechanically similar to the well-known rotary lineswitch having no normal position, while the circuits thereof have been altered in accordance with the present invention.

The start relays SR, shown at the bottom of Fig. 3, are arranged to start alternate finders included in the group of finder-connector links in the manner to be more fully described hereinafter.

The connector switch, shown in Fig. 4 is mechanically similar to the finder, but instead of automatically hunting for a marked potential as the finder does, the connector is directly controlled, in part, by impulses to a certain set of contacts and is thereafter automatically rotated to normal position after termination of a call. Near the lower left-hand corner of Fig. 4, the chain start circuit through the remaining finder connector links is diagrammatically illustrated in the dotted rectangle.

Near the lower center portion of Fig. 4, a dial-tone relay 453 for generating dial tone is common to all of the finder connector links. To the right center of Fig. 4, the dotted rectangle illustrates the connections for enabling local subscribers to make conference calls. The resistance shown in the dotted rectangle is connected to only one of the switch banks and is not multiplied, while the conductors 462 and 472 extending to relay 468 are common and are multiplied between the banks of the various connector switches.

The code-call finder switch shown in Fig. 5, is mechanically similar to the finder of the finder connector link and also hunts for a marked potential. The relays associated with this switch are for enabling a calling subscriber to send out ringing current impulses over the code-call circuit in accordance with dialling impulses. The code-call signalling circuit comprises the conductors 542 and 544 which extend to signals as required. The code-call switch is accessible from the banks of the connector switch.

The transfer sequence switch TSS shown in Fig. 6 is mechanically similar to the aforementioned rotary lineswitch, being, however, of a small capacity and permits only one call at a time to be transferred. The busy-tone relays, BTR, comprise relays when operated for generating a busy tone, while the ringing interrupter relays, RIR, comprise relays for generating interrupted ringing current. Relay 621 is equipped with a vibrating armature 626 which vibrates between its upper and lower contacts when the relay 621 is de-energized. The alarm signalling relays ASR are provided for transmitting alarm signals over a two-conductor trunk to the main telephone exchange when trouble occurs.

In Figs. 7 and 8, one of a number of two-way trunk circuits is shown connecting the local private automatic exchange with one of the telephone company's exchanges which may be either manual or automatic. The trunk circuits terminate in the private automatic exchange in trunk relay groups and finder switches for connecting the trunks to the local subscribers' lines. The trunk finders are mechanically similar to the local finders while the circuits of the relay groups, however, are modified to permit two-way working. At the bottom of Fig. 7, relay 768 shown in the dotted rectangle, is provided for sequentially taking the trunk finders into use. The dotted rectangle shown to the lower right of Fig. 8 diagrammatically illustrates a portion of the chain circuit extending through the trunk circuits. The correspondingly numbered armatures illustrate similar armatures on the succeeding trunk circuits. Relay 833, shown near the upper portion of Fig. 8, is the incoming signalling relay which is common to all of the trunk circuits, and

which when operated, closes the circuit for operating the incoming trunk signals. When the trunk circuit, shown in Fig. 8, extends to an automatic exchange, a dotted strap shorting the winding of relay 802 is provided, while this strap is cut when the trunk circuit extends to a manual exchange.

In the finders shown in Figs. 3, 5, and 7, relays 309, 508, and 712 are polarized relays of the type disclosed in Patent No. 1,673,884, issued June 19, 1928, to H. C. Pye. The core of these switching relays are provided with two windings which are separated by a magnetic spacing member, a projection of which extends back and forms a back stop against which the armature of the relay rests. The winding on the heel end of the relay is the magnetizing coil, and the flux produced thereby traversing the path including this magnetic iron back stop, which is in shunt of the air gap, and no amount of flux strength in this magnetizing coil will cause the armature to operate. A very small current in the second operating winding of the relay, when in the same direction as the magnetizing winding, will cause the relay to operate. The use of these relays as testing relays permits the calling line to be marked in the finder banks with a potential through relatively high resistance and impedance and prevents undesired disturbances in the searching circuits. All the relays of this type have been shown in the drawings with lugs extending from their center portions.

Although a plurality of batteries are shown connected to the various relays in the drawings, it will be understood that there is but one main battery and that the battery-feed leads to the various switches are fused separately as indicated by the letters MB in a circle in the various sheets of drawings.

Having described the equipment and apparatus, a detailed description of the operation will now be given. For this purpose, it will be assumed that subscriber S desires to call subscriber S'. In order to call subscriber S', subscriber S will remove the handset from the cradle and dial digits 4 and 2 corresponding to the number of subscribers' lines, such as S'. Responsive to the removal of the handset from the cradle, a circuit may be traced for energizing common-line relay 7 in series with two-step cut-off relay 3 as follows: from ground through the winding of relay 7, armature 4, conductor 1, impulse springs of the calling device CD, transmitter T, upper spring of the cradle springs CS, middle winding of the induction coil IC, conductor 2, armature 6, and through the upper winding of relay 3 to battery. Relay 3 energizes and at this time operates only its armature 5 to mark the line S as calling in the banks of the finder over conductor 11. Common line relay 7, upon energizing, at armature 8 grounds the common start con-

ductor 9 which extends to start relay 390 in Fig. 3. Relay 390, upon energizing, at armature 394 closes an obvious circuit for relay 391, and the latter relay at armature 396 prepares a circuit for energizing relay 392 which relay at this time is short circuited. At armature 395, relay 390 prepares a circuit for short circuiting relay 391, and at armature 393, grounds start conductor 377 in the finder chain circuit. The start relays 390 to 392, inclusive, are so arranged that when common conductor 9 is first grounded, relays 390 and 391 operate. Relay 391 locks to armature 398 and at armature 396 prepares the circuits to relay 392, when ground is removed from conductor 9, relay 390 releases, while relay 391 is maintained energized in series with relay 392, which now energizes since the short circuit has been removed. Relay 392 at armature 397 switches the start circuit from conductor 377 to conductor 378. When conductor 9 is again grounded, relay 390 grounds the start conductor 378 instead of conductor 377. Armature 395 closes a short circuit around relay 391 which de-energizes, while relay 392 is maintained operated. When ground is removed from conductor 9, relays 390 and 392 deenergize with the result that all of the relays are now in the normal position. The alternate ground-
ing of conductors 377 and 378 causes successive finder connector links to be taken into use in response to successive calls.

When conductor 377 is grounded, a circuit may be traced for energizing start relay 310 of the finder as follows: from grounded conductor 377, armature 325 and its resting contact, armature 331 and its resting contact, and through the winding of start relay 310 to battery. Relay 310, which is fairly slow to operate and release, at armatures 319 and 320 prepares the circuits for testing relay 309. The circuit through the lower winding of test relay 309 merely energizes the electro-polarized winding to prepare the test relay for operation when the test wiper 303 encounters a calling potential. At armature 321, start relay 310 completes an energizing circuit for stepping relay 308 by way of armature 318 and its resting contact and interrupter springs 316 of the motor magnet 307. Stepping relay 308, upon energizing, closes a circuit by way of armatures 321 and 318 for energizing the motor magnet 307. Motor magnet 307 positions its pawl preparatory to stepping the wipers of the finder and at armature 316 opens the circuit of stepping relay 308. Relay 308, upon deenergizing, at armature 317 opens the circuit of a stepping magnet 307, whereupon the magnet 307 de-energizes and steps the wipers of the finder one step. At armature 316 motor magnet 307, upon deenergizing, reestablishes the circuit for stepping relay 308 with the result that the stepping relay energizes and again

completes the circuit for energizing the motor magnet 307. This interaction between the stepping magnet 307 and the stepping relay 308 continues until test wiper 303 encounters a calling potential, in this case a negative battery potential. When test wiper 303 reaches the calling line, a circuit may be traced for energizing relay 309 in series with relay 3 as follows: from ground by way of armature 319, upper operating winding of test relay 309, test wiper 303 in engagement with the fourth bank contact, conductor 11, armature 5, and through the lower winding of relay 3 to battery. Relay 3 is energized through its second step, thereby operating armatures 4 and 6 to disconnect the common line relay 7 and to disconnect the upper winding of relay 3 from line conductor 2. Common line relay 7 deenergizes and at armature 8 removes ground from the common start conductor 9 with the result that the start relays SR in Fig. 3 operate in the same manner as previously described.

Returning now to the finder shown in Fig. 3, test relay 309, upon energizing, at armature 318 closes a circuit for energizing relay 312 over an obvious circuit and also opens the circuit extending to the stepping relay 308 and stepping magnet 307. The finder, therefore, comes to rest in engagement with the wipers 301 to 306, inclusive, in engagement with their fourth bank contacts. Relay 312, upon energizing, at armature 329 opens a point in the circuit of alarm relay 650; at armature 331 opens a point in the circuit of start relay 310 at its resting contact, and at its working contact closes a point in the chain circuit to the next finder connector link. Start relay 310 does not immediately deenergize on account of the copper slug, diagrammatically illustrated by the upper black portion, which renders the same slow-to-release as well as slow-to-energize. At armature 327, relay 312 grounds test wiper 303, thereby grounding conductor 11 and making the line S busy; and at armature 328 prepares a locking circuit for relay 311. At armatures 334 and 332 relay 312 closes the circuit for the line relay 407 for the connector as follows: from ground through the lower winding of line relay 407, conductor 375, armature 332, armature 326, wiper 306 in engagement with the fourth bank contact, line conductor 2 over the calling loop of subscriber S to line conductor 1, fourth bank contact and wiper 301, armature 333, armature 334, conductor 363 to the upper winding of line relay 407 to battery. Line relay 407, upon energizing, at armature 416 completes a circuit for energizing slow-to-release relay 408 over an obvious circuit. Relay 408 at armature 421 grounds conductor 367 before relay 310 fully deenergizes in order to hold relay 312 in operated position. At armature 418, release relay 408 prepares a circuit for switching relay 414; 130

at armature 420 prepares a point in the impulsing circuit; and at armature 419 prepares a holding circuit for relays 411, 414, and 314 and also closes a circuit for energizing relay 413 by way of armature 444 and its resting contact. Relay 413 at armature 437 prepares a circuit for the series relay 409; at armature 438 prepares a circuit for relay 410; at armature 439 places another ground connection on conductor 367, at armature 449 removes ground from the multiplied bank contacts and conductor 466, at armature 440 completes a circuit for energizing the differentially-wound dial-tone relay 453 which now operates in the manner of a buzzer to generate dial tone, and at armature 441 closes a circuit for connecting dial tone to the calling subscriber's line. The dial-tone circuit may be traced as follows: from armature 454 of the dial-tone relay 453, conductor 456, normal-position bank contact and wiper 406, armature 441, resting contact of armature 436 and said armature, armature 429, through the two condensers in series, conductor 375 from whence the dial tone may be traced over the loop circuit previously traced.

In response to the dial tone, subscriber S will then operate the calling device CD in accordance with the number of the desired subscriber, in this case subscriber S' or number 4-2. The operation of the calling device for the first digit interrupts the line circuit of line relay 407 four times, thereby causing line relay 407 to deenergize four times. Release relay 408 as illustrated in the drawings has a copper sleeve around its core, thereby making the same slow-to-release, and in this case, release relay 408 does not deenergize during the dialling period. Upon the first de-energization of line relay 407, a circuit may be traced for energizing stepping magnet 415 as follows: from ground by way of the normally closed springs controlled by armature 416, armature 420, armature 434, armature 446, and through the winding of motor magnet 415 to magnet. Motor magnet 415 energizes and operates its pawl preparatory to stepping the wipers of the connector. A branch of this circuit extends from armature 446, by way of armatures 437 and 417 for energizing slow-to-release series relay 409. At armature 423, series relay 409 closes a shunt circuit around armature spring 434 controlled by busy relay 412; at armature 422 prepares a point in the circuit for busy relay 412; and at armature 424 and its working contacts closes a circuit for energizing relay 410 as follows: from ground by way of armature 424, armature 348, wiper 404 in normal position, conductor 369, armature 322 which by this time has closed, conductor 368, normally closed spring controlled by armature 428 through the resistance and upper winding of relay 410 to battery. Relay 410 at armature 425 opens a point in the test circuit;

at armature 426 prepares a point in the circuit for relay 314, at armature 427 prepares a point in the automatic stepping circuit for the connector switch in case the digit 4 is dialled; at armature 428 completes a locking circuit for itself from closed armature 424; and at armature 429 disconnects dial-tone from the calling loop.

When line relay 407 energizes after the first interruption or impulse, the circuit of release relay 408 is again closed and the circuit through the motor magnet 415 and series relay 409 is interrupted. Series relay 409 is slow to release and also maintains its armatures attracted during impulsing. The motor magnet 415, however, releases its armature, thereby causing the wipers 401 to 406, inclusive, to take one step. Since four impulses are being sent, the wipers 401 to 406, inclusive, will take four steps and come to rest on their fourth bank contacts. Wiper 404 is, therefore, in engagement with the multiply connected contacts 467; and when series relay 409 deenergizes shortly after the impulsing period, relay 410 is maintained energized over the following circuit: from ground by way of contacts 467, wiper 404, armature 438, armature 428 and its working contact, and through the resistance and upper winding of relay 410 to battery. Another result of the deenergization of series relay 409 is the establishment of an automatic stepping circuit for magnet 415 as follows: from ground by way of contacts 467, wiper 404, armature 438, armature 424 and its resting contact, armature 427, armature 447, interrupter springs 448 and through the winding of magnet 415 to battery. The motor magnet 415 operates in a buzzerlike manner until wiper 404 no longer encounters a grounded contact, the first ungrounded contact being the fourteenth contact accessible to wiper 404. Relay 410 also deenergizes when wiper 404 reaches its fourteenth contact.

Before proceeding with the dialling operation of the second digit, it may be advisable to describe the operations which take place in case the digit 3 were dialled instead of the digit 4. In this case, the wipers 401 to 406, inclusive, will come to rest on their third set of contacts. Wiper 404 does not, therefore, encounter ground with the result that relay 410 deenergizes when its circuit is opened by relay 409. The wipers are not automatically stepped as previously described. From this point on the dialling of the second digit directly operates the connector wipers to the contacts of the desired line.

Returning now to the first description and responsive to the dialling of the digit 2, two impulses are sent out over the calling loop to operate line relay 407 as before. The series relay 409 and motor magnet 415 operate in the same manner as described, but relay 410 does not energize because its original energizing

circuit was opened when wiper 404 moved off normal. In response to the operation of the motor magnet 415, the wipers 401 to 405, inclusive, are operated into engagement with their sixteenth bank contacts terminating the conductors associated with the line of subscriber S'.

In case the line is busy, there will be a ground potential on conductor 110, and a circuit for energizing busy relay 412 before series relay 409 deenergizes may be traced as follows: from grounded conductor 110, wiper 403, normally closed springs controlled by armature 443, armature 426, armature 422 and its working contact and through the winding of busy relay 412 to battery. Shortly after the last dialled impulse, relay 409 deenergizes and at the make-before-break springs of armature 422 completes a locking circuit for the busy relay 412 as follows: from ground by way of armature 418, armature 433 and its working contact, normally closed springs controlled by armature 422 and through the winding of busy relay 412 to battery.

At armature 435, busy relay grounds the busy and generator-start conductor 371, thereby energizing relay 615 over the common conductor 360. Relay 615 at armature 626 starts the ringing vibrator by energizing the differential relay 640 through its left-hand winding which operates the vibrator 641 to the left to close a circuit through the right-hand winding in opposition to the left-hand winding. Relay 640, being differentially wound, releases its vibrator 641, thereby causing the vibrator to swing to the right and open a circuit extending through the right-hand winding. The vibrator 641, therefore, vibrates and closes alternate circuits through windings 642 and 643 of the induction coil to set up current flow in opposite directions. This current flow is induced in the winding 644 which transmits pulsating or ringing current out over the common ringing conductor 457 when relay 620 is energized. At armature 624 relay 615 closes a circuit for energizing relay 620 over armature 637 and its resting contact. Relay 620 at armature 625 closes a circuit for energizing relay 621 by way of armature 639. Relay 621 attracts the vibrating armature 636 to close its lower contact and thereby close a circuit for energizing slow-acting relay 622 by way of armature 634. After an interval, relay 622 energizes, and at armature 637 opens the circuit of slow-to-release relay 620 and at armature 638 closes a circuit for energizing slow-to-release relay 623. Relay 623 at armature 639 opens the circuit of relay 621 which deenergizes and releases its vibrating armature 636. Armature 636 vibrates between its upper and lower contacts to hold relay 622 energized for a predetermined period, after which relay 622 de-

energizes to complete a circuit for reenergizing relay 620 which has in the meantime de-energized. The deenergization of relay 622 also opens the circuit of relay 623 which also deenergizes after a predetermined period. The deenergization of relay 623 again completes the circuit of relay 621 which reenergizes to start the same cycle of operations. This cycle of operations continues as long as relay 615 is energized, and, therefore, due to the intermittent operation of relay 620, common conductor 457 is intermittently grounded and connected to the source of ringing current at coil 644.

Relay 615, upon energizing, at armature 625 completes a circuit for energizing relay 616 and busy interrupter relay 618. Relay 618 is differentially wound and operates like a buzzer to open and close springs 630. Relay 616 at armature 627 opens the short circuit from around relay 617, thereby causing the energization of the latter relay. Relay 617 at armature 629 closes the busy-tone generated by relay 618 to the common busy-tone conductor 459. At armature 628, relay 617 closes a short circuit around relay 616 which deenergizes after an interval and reestablishes the short circuit around relay 617 which also deenergizes after an interval. When relay 617 deenergizes, the tone is disconnected from conductor 459 at armature 629, and at armature 629 the short circuit around relay 616 is removed and relay 616 reenergizes to again reenergize relay 617. This cycle of operations continues as long as ground is connected to conductor 360.

Returning now to the connector switch in Fig. 4, and responsive to the energization of the busy relay 412, busy-tone may be traced from conductor 459 over the working contact of armature 436 and said armature, armature 429 and over the calling loop. In response to the busy tone, the calling subscriber will replace the handset on the cradle and the finder connector link in Figs. 3 and 4 will be released in a manner to be subsequently described.

Assuming now that line S' was idle when called, instead of busy, the busy relay 412 would not be energized, and when relay 409 deenergizes after the last impulse, a circuit may be traced for energizing switching relay 414 in series with the two-step cut-off relay 113 as follows: from ground by way of armature 418, armature 433 and its resting contact, lower winding of switching relay 414, resting contact and armature 422 and said armature, armature 425, normally closed springs controlled by armature 443, wiper 403 in engagement with the bank contact terminating conductor 110, conductor 110 to Fig. 1, and through the lower winding of two-step cut-off relay 113 to battery. Switching relay 414 operates its armature 445 to complete a circuit from grounded armature 419

in order to fully operate the relay and to complete a locking circuit for itself. At armature 443, relay 414 grounds the test wiper 403 to busy the called line and to maintain the cut-off relay 113 of the called line in operated position. At armature 444 and its resting contact relay 414 opens the circuit of relay 413 which now deenergizes and at its working contact prepares a circuit for locking relay 314. At armature 446, relay 414 opens the point in the impulsing circuit; at armature 447 opens a point in the automatic restoring circuit of the connector, at armature 450 grounds conductor 371 to start the busy and ringing interrupter relay as previously described; at armature 451 closes a ring-back circuit to the calling subscriber by way of conductor 457, resting contact of armature 432 and said armature, armature 451, resting contact of armature 436 and said armature, armature 429 and thence over the calling loop; and at armatures 442 and 452 connects ringing current to the called line. Relay 413, upon deenergizing, at armatures 439 and 449 prepares circuit for automatically restoring the connector switch to its normal position, and at armature 40, opens the circuit to the dial-tone relay 453. The ringing circuit for ringing the called subscriber may be traced as follows: from ringing interrupter lead 457, resting contact of armature 432 and said armature, armature 452, wiper 406 in engagement with the bank contact terminating conductor 132, conductor 132, through the condenser and ringer bell RB of substation S', conductor 131, wiper 401, armature 442, armature 430 and its resting contact and through the lower winding of ring cut-off relay 411 to battery.

When cut-off relay 113 energizes in series with switching relay 414, relay 113 operates all its armatures to disconnect the common line relay 117 at armature 114; at armature 116 disconnects the upper winding of relay 113 from conductor 132 and at armature 115 connects conductor 110 to conductor 111 to busy the line in the banks of the local finder and code-call finder.

When subscriber S' removes the handset from the cradle in response to the operation of the ringer bells RB, ring cut-off relay 411 is energized over the called subscriber's loop and said relay at armature 431 completes a locking circuit for itself. At armatures 430 and 432, relay 411 disconnects the ringing current from the line conductors and connects through the talking conductors indicated in heavy black lines. A circuit may now be traced for the back-bridge or battery-feed relay 410 as follows: from ground through the lower winding of relay 410, working contact of armature 432 and said armature, armature 452, wiper 406, conductor 132, resting contact of spring 151 and said spring in the sub-base SB, Fig. 1, con-

ductor 102, through the substation circuit to conductor 101, push-button springs 150, conductor 121, spring 156 and its resting contact, conductor 181, wiper 401, armature 442, armature 430 and its working contact, and through the upper winding of back-bridge relay 410 to battery. Back-bridge relay 410 feeds talking battery to the called subscriber over the circuit just traced. Relay 410, upon energizing, at armature 429 disconnects ring-back tone; at armatures 428 and 427 prepares circuits for maintaining relay 410 in operated position during the automatic restoration of the connector to normal; and at armature 426 completes a circuit for energizing relay 314 as follows: from ground by way of armature 419, armature 444 and its working contact, armature 426, conductor 366 and through the winding of relay 314 to battery. At armature 341, relay 314 completes a locking circuit for itself over conductor 365 independent of relay 410; at armature 342 connects the upper winding of relay 313 in series with wipers 302 and 402 for a purpose to be more fully described hereinafter in connection with the transfer of a call; at armature 343 removes ground for generator start conductor 360; and at armature 335 completes the talking circuit over the heavy black lines between subscribers S and S'. Relays 312 and 314 in the finder switch, and relays 407, 408, 410, 411, and 414 in the connector are energized during conversation.

After conversation and responsive to the called subscriber replacing his handset on the cradle, relay 410 deenergizes. Responsive to the calling subscriber replacing his handset on the cradle, line relay 407 deenergizes, and at armature 416 opens the circuit of release relay 408 which deenergizes after a short interval. At armature 419, relay 408 removes holding ground from relays 411, 414, and 314 which now deenergize; at armature 421 removes ground from conductor 367, thereby deenergizing hold relay 312, and at the resting contact of armature 421, closes a circuit for automatically restoring the connector wipers to normal position. This circuit may be traced as follows: from ground at armature 449, or from ground at the multiply connected contacts 467, wiper 404, normally closed springs controlled by armature 439, armature 421 and its resting contact, armature 447, interrupter springs 448 and through the winding of motor magnet 415 to battery. The motor magnet operates in the manner of a buzzer to step the wipers 401 to 406, inclusive, until the wiper 404 loses ground which it does when it reaches its normal position or the position shown engaged by the wiper in the drawings. The deenergization of relays 312, 314, 411, and 414 and the return-to-normal of the connector wipers places this finder-connector link in the condition shown

in the drawings, in readiness to receive another call.

In case a subscriber should initiate a local call when all the local finder connector links are busy, all of the armatures, such as armatures 331 and 331', in the various finder-connector links would be operated with the result that no circuit is completed to a start relay, such as relay 310 and, therefore, no finder connector link would be seized and the calling subscriber would not receive dial tone, thereby indicating such a busy condition.

Incoming calls

It will now be assumed that an incoming trunk call is received over the conductors 840 and 841 from the distant exchange. When an incoming call is received over conductors 840 and 841, relays 806 and 807 operate. Relay 806 is a very high wound relay and operates in response to either the ringing current or during the silent period, while relay 807 is an AC relay which operates only in response to ringing current. The circuit for energizing ring-up relay 807 may be traced as follows: from generator at the main exchange, conductor 840, condenser and lower winding of relay 807, resting contact of armature 828 and said armature, armature 824 and over trunk conductor 841 back to the generator. Relay 806 is operated over the trunk conductors 840 and 841 and at armature 826 completes an obvious circuit for energizing slow-to-release relay 804. Relay 807 at armature 827 completes a locking circuit for itself by way of armatures 819 and 747; at armature 828 and its resting contact opens its original energizing circuit and bridges the AC signalling relay 808 across the trunk conductors 840 and 841; at armature 829 completes a circuit for energizing relay 710 over conductor 759; and at armature 830 prepares a point in the incoming start circuit for the trunk finder. Relay 808 operates in response to ringing current and at armature 831 closes a circuit for signalling relay 833 which relay, at armature 834, completes a circuit for operating the incoming trunk signals over conductor 835. Relay 804, upon energizing, at armature 820 completes a circuit for energizing at relay 803; at armature 819 completes the locking circuit for ring-up relay 807; at armatures 821 and 822 complete points in the chain circuits; and at armature 818 completes a circuit for energizing slow-to-operate relay 650 which relay, however, does not have time to energize before its circuit is opened at armature 816 by relay 803. At armature 814, relay 803 disconnects relay 802 from talking conductor 754 and connects the trunk conductor 840 in place thereof; at armature 816, relay 803 prepares a locking circuit for itself and at armature 817 prepares a locking circuit for relay 716.

Any subscriber equipped with an "ANS" key in their sub-base SB may answer this call. It will be assumed that subscriber S' answers the incoming trunk call. To do this, subscriber S' operates the "ANS" key 70 and removes the handset from the cradle. In response to the operation of the answer key, springs 151, 152, 155, and 156 are operated in the manner previously described, and a circuit may, therefore, be traced from ground through springs 155, normally closed springs controlled by armature 143 and through the winding of relay 141 to battery. Relay 141 at armature 147 prepares a locking circuit for itself; at armature 146 and 80 its working contact completes a circuit for the common incoming line relay 161; and at armature 148 disconnects the outgoing test conductor 167 and connects up the incoming test conductor 166. A circuit may now be 85 traced for relays 161 and 140 as follows: from ground through the winding of the common incoming line relay 161, working contact of armature 146 and said armature, armature 142, working contact of springs 90 151, conductor 102 over the subscriber's loop to conductor 101, springs 150, conductor 121, spring 156 and its working contact, armature 145, and through the upper winding of two-step cut-off relay 140 to battery. Cut-off relay 140 operates in its first step only to close armature 144 to connect a negative battery potential from the lower winding of relay 140 to conductor 166 which terminates in the test bank contact accessible to test 100 wiper 703 of the trunk finder. Common line relay 161 at armature 163, grounds the common incoming start conductor 165 to complete a circuit by way of conductor 765, armature 830 and its working contact, conductor 763, armature 745 and its resting contact, armature 736 and its resting contact and through the winding of slow-to-operate start relay 711 to battery. Start relay 711 at armature 726 completes an energizing circuit 110 through the upper winding of relay 709 which energizes and locks up through its lower winding; at armature 727 prepares the operating circuit for three-pole test relay 712, and at armature 728 completes a circuit 115 for the lower electro-polarizing winding of relay 712 which relay, as previously described, will not operate until a circuit is completed through its operating winding in the proper direction. At armature 729, relay 711 completes a circuit for energizing stepping relay 708 as follows: from ground by way of armature 729, armature 730 and its resting contact, winding of relay 708 and through the interrupter springs 717 of the 120 motor magnet 709 to battery. Stepping relay 708 at armature 718 completes a circuit for energizing the motor magnet 707 and the motor magnet, upon energizing, at its 125 interrupter springs 717 interrupts the cir- 130

cuit of the stepping relay 708 which now deenergizes. When stepping relay 708 is fully deenergized, said relay at armature 718 opens the circuit of the motor magnet 707 with the result that motor magnet 707 5 steps the switch wipers 701 to 706, inclusive, and at interrupter springs 717 reestablishes the circuit for stepping relay 708. This interaction between stepping relay 708 and motor magnet 707 continues until test wiper 10 703 encounters a calling potential, in this case negative-battery potential. When wiper 703 engages the bank contact terminating conductor 166 circuit may be traced for energizing the two-step cut-off relay 140 in series with the operating winding of the three-pole relay 712 as follows: from ground by way of armature 727, upper operating winding of test relay 712, armature 742 and its 15 resting contact, armature 723 and its working contact, test wiper 703, conductor 166, working contact of armature 148 of said armature, armature 144, and through the lower winding of relay 140 to battery. Two-step relay 140 energizes through its second 20 step over this circuit to disconnect the common-line relay 161 at armature 142; to complete the locking circuit for relay 141 and to disconnect the upper winding of relay 140 from talking conductor 172. Common 25 line relay 161 deenergizes and at armature 163 removes ground from the incoming start conductor 165. In the trunk finder, the three-pole test relay 712 energizes over the above-traced circuit and at armature 730 and its 30 resting contact opens the stepping circuit, and at its working contact completes a circuit for energizing relay 713 from grounded armature 729. At armature 732, relay 713 grounds the test wiper 703 to busy line S' to other trunk finders; at armature 733 prepares a locking circuit for itself; at armature 735 opens a point in the circuit of the 35 slow-to-operate start relay which maintains its armatures attracted for a short time thereafter and prepares a point in the chain circuit to the succeeding trunk finder; and at armatures 731 and 736 completes the talking circuit between subscriber S' and the 40 main exchange as well as completing a circuit for energizing relay 801. The circuit for energizing relay 801 may be traced as follows: from ground applied to conductor 840 at the main exchange, armature 814 and 45 its working contact, conductor 754, armature 731, wiper 701, conductor 171, through the sub-station circuit and sub-base keys over the circuit previously traced to conductor 172, wiper 706, armature 736, conductor 766, 50 winding of relay 801, resting contact and armature 818 and said armature, and over trunk conductor 841 to battery. At armature 810, relay 801 completes an energizing circuit for slow-to-release relay 805. At armature 824, relay 805 opens the circuit of relay 55 806 which deenergizes; at armature 823 closes the locking circuit for relay 803, and at armature 825 completes a circuit for energizing relay 716. Slow-to-release relay 804 deenergizes a short interval after relay 806 60 deenergizes and at armature 819 opens the locking circuit of ring-up relay 807; at armature 820 opens the original energizing circuit of relay 803 which is now locked up over armature 823. When relay 716 in Fig. 75 7 energizes, said relay at armature 747 opens the locking circuit of relay 807 whereupon the latter relay deenergizes and opens the circuit of relay 808. It should be mentioned at this time, however, that in response to the 80 operation of the switching-through relay 713 in Fig. 7, a bridge including the subscriber's loop was placed across the trunk conductors 840 and 841 to automatically cut-off the ringing current. Relay 808, upon deenergizing, 85 at armature 831 opens the circuit of the common signalling relay 833 with the result that the incoming signals are no longer operated in response to this trunk call. At armature 748, relay 716 prepares a circuit for relay 90 715 which will be effective only in case the trunk call should be transferred to another local subscriber as will be more fully described hereinafter. At armature 749, relay 95 716 completes a locking circuit for itself over conductor 758 and armature 817; at armature 750 completes a locking circuit for switch-through relay 713 from grounded armature 750, resting contact of armature 743 and said armature, normally closed springs 100 controlled by armature 739, armature 733, and through the winding of relay 713 to battery. At armature 751, relay 716 completes the locking circuit for relay 710, and at armature 752 completes a point in the chain circuit. The subscriber S' is now connected to the calling subscriber over the heavy talking conductors and both the calling and called subscribers receive their talking battery from the main exchange. The calling and called 105 subscribers may now converse as desired. 110

In response to the replacement of the handset by the subscriber S', the "ANS" key and spring assemblies shown in the sub-base SB are automatically restored to normal or the position shown in the drawings to open the circuit through relay 801. Relay 801, upon deenergizing at armature 810 opens the circuit of relay 805 which deenergizes and at armature 823 opens the locking circuit of relay 803 and at armature 825 opens a point in the original energizing circuit of relay 716. After a short interval, relay 803 deenergizes and at armature 814 disconnects the incoming trunk conductor 840 from the talking conductor 754; at armature 816 opens a point in its own locking circuit; and at armature 817 opens the locking circuit of relay 716. At armature 750 relay 716, upon deenergizing, opens the locking circuit of 115 120 125 130 135

relay 713, and at armature 751 opens the locking circuit of relay 710. Relays 710 and 713 thereupon deenergize and the trunk finder and relays shown in Figs. 7 and 8 are now in normal position in readiness to receive another incoming call or an outgoing call.

Outgoing calls

- 10 It will now be assumed that subscriber S² desires to call a subscriber in the main automatic or main manual exchange over one of the trunk circuits, such as shown in Figs. 7 and 8. Subscriber S² thereupon operates the "OUT" key in the sub-base SB, thereby operating the bar 261 in a horizontal direction to operate springs 251, 252, 256, and 258. In response to the removal of the handset from the cradle, springs 253 are opened, springs 254 are closed, and the locking bar 260 is operated to lock spring 252 in operated position. A circuit may now be traced from ground through the common outgoing line relay 260, terminal 203 connected to conductor 204, resting contact of armature 246 and said armature, armature 242, resting contact of armature 291 and said armature, working contact and springs 251 and said spring, conductor 202 through the calling subscriber's loop to conductor 201, push-button springs 250, conductor 221, spring 256 and spring 258, armature 293 and its resting contact, armature 297 and its resting contact, and through the upper winding of two-step relay 240 to battery. Two-step relay 240 energizes and operates only armature 244 in its first step at this time to connect the calling potential extending from the lower winding of two-step relay 240 to the outgoing test bank 40 contacts accessible to wipers 702 of the trunk finders such as shown in Fig. 7. The common outgoing line relay energizes over the above-traced circuit and at armature 262 grounds the common outgoing start conductor 164 to complete a circuit for the start relay of the first idle trunk finder.

For the purpose of describing the start chain circuit of the trunk finders, it will be assumed that the first trunk finder in the 50 chain is busy with an incoming call and that the second trunk finder is busy in an outgoing call, and, therefore, when common start conductor 164 is grounded, the start circuit will extend by way of armature 722 and its 55 resting contact, conductor 764, armature 822 and its resting contact, conductor 763, armature 745 and its resting contact, armature 735 and its working contact, conductor 762 to the succeeding trunk finder, armature 722 60 and its working contact, and conductor 762 to the next succeeding or third trunk finder. In case this call should come in before relay 804 in a busy-trunk finder has deenergized in response to the deenergization of relay 806, 65 the chain circuit is taken through armature

822 and its working contact to the succeeding trunk finder. In case the trunk finder may be busy in a transfer call, the start circuit is completed by way of armature 745 and its working contact instead of its resting contact. In case all of the trunk finders are busy, the start circuit extends through the chain circuit of all of the trunk finders in the manner previously described to conductor 671, thereby completing a circuit for relay 619 to initiate the operation of the busy-tone relays 616, 617, and 618 as previously described. At armature 632 all-trunks-busy relay 619 closes the busy-tone circuit as follows: from vibrating armature 630, interrupter armature 629, armature 632, the condenser and conductor 106, through Fig. 5 to Fig. 2, conductor 206, and through the winding of common outgoing line relay 260 and over the calling subscriber's loop circuit. The calling subscriber may either replace his receiver or wait until an idle trunk circuit is available. It is believed advisable at this time to describe another branch of the chain circuit which has been provided to insure the successive seizure of trunk circuits when making outgoing calls. Armature 721, in each of the trunk finders, connects ground to conductor 760 whenever such trunk finder is taken into use. Conductor 760 of the first 95 trunk finder extends to terminal such as terminal 753 in the succeeding trunk finder and so forth through the chain. As each trunk is taken into use for an outgoing call, the relay 709 is energized and locked, and when the last 100 trunk finder is taken into use in an outgoing call, a circuit may be traced from armature 721 of the last trunk finder for energizing slow-to-operate relay 768 over conductor 767. Relay 768 at armature 769 opens the locking circuit of all relays 709 in the various trunk finders to cause their release so that the sequence of seizing the trunk circuits on succeeding calls will start all over again. When the relay 709 in the last trunk circuit is deenergized, the relay 768 will also be energized after an interval and again prepare the locking circuits for the relays, such as relay 709, in the trunk circuits. It will now be assumed that the trunk finder shown in Fig. 7 is the 115 first idle trunk finder, and, therefore, when the common outgoing start conductor is grounded, a circuit may be traced for the start relay 711 over armature 722 and its resting contact, conductor 764, armature 822 and its resting contact, conductor 763, armature 745 and its resting contact, armature 735 and its resting contact, and through the winding of start relay 711 to battery. Start relay 711 at armature 726 completes a circuit for energization relay 709 which now locks up over its armature 720, and at armatures 727, 728, and 729 prepares the test circuit through the three-pole test relay 712 and completes the stepping circuit for the stepping 125 130

relay 708 and motor magnet 707 in the same manner as described for an incoming call. In response to the operation of the stepping relay 708 and motor magnet 707, the wipers 701 to 706, inclusive, of the trunk finder are operated step-by-step in the manner previously described until the outgoing test wiper 702 encounters the negative battery calling potential applied to conductor 267. When test wiper 702 encounters the bank contact terminating conductor 267, a circuit may be traced for energizing the three-pole switching relay 712 in series with the two-step relay 240 as follows: from ground at armature 727 through the upper operating winding of relay 712, armature 742 and its resting contact, armature 723 and its resting contact, wiper 702, conductor 267, resting contact of armature 248 and said armature, armature 244 and through the lower winding of relay 240 to battery. Two-step relay 240 energizes and operates its armatures through their second step to disconnect the common line relay 260 at armature 242, and to disconnect the upper winding of relay 240 from the lower talking conductor 272. In the trunk finder the three-pole test relay 712 is energized over the above-traced circuit, and at armature 730 opens the stepping circuit at its resting contact, and at its working contact completes a circuit for energizing switch-through relay 713. At armature 732, relay 713 short circuits the upper operating winding of relay 712 and also connects ground to test wiper 702 to make the line S^2 busy. At armatures 731 and 736 connects the calling subscriber's loop circuit to conductors 754 and 766 over the following circuit: conductor 754, armature 731, wiper 701, conductor 271, resting contact of armature 291 and said armature, working contact of spring 251 and said spring, conductor 202, over the calling substation circuit to conductor 201, push-button springs 250, conductor 221, springs 256 and 258, armature 293 and its resting contact, conductor 272, wiper 706, and through armature 736 to conductor 766.

The operation of the trunk finder is slightly different dependent upon whether the trunk conductors 840 and 841 extend to a manual or an automatic exchange. In either case, ground is disconnected from the trunk conductor 840 at the main exchange, while the conductor 841 extends to a signalling relay and negative battery in case of a manual exchange, or extends through the line relay to battery of an incoming lineswitch in case the main exchange is an automatic exchange. In addition, relay 802 in Fig. 8 is permanently short circuited in case the trunk conductors 840 and 841 extend to an automatic exchange, while the short circuit is removed from around said relay in case the trunk conductors extend to a manual exchange. It will first be assumed that the trunk conduc-

tor extends to a manual exchange and, therefore, a circuit may be traced from ground through the winding of relay 802, through the normally closed springs controlled by armature 814, conductor 754, and from thence over the calling loop to conductor 766, winding of relay 801, resting contact of armature 813 and said armature, conductor 841, and through the incoming signalling relay at the main manual exchange to battery. Relays 801, 802, and the signalling relay in the manual exchange operate over the above-traced circuit and the signalling relay in the manual exchange operates a signal in the well-known manner to indicate an incoming call to the manual operator thereat. Relay 801 at armature 810 completes a circuit for energizing relay 805 and relay 802 at armature 811 also completes a circuit for energizing relay 805, and at armature 812 connects negative battery to the lower terminal of relay 801 to maintain this relay energized, and at armature 813 connects ground to conductor 841 to maintain the incoming signal relay operated until the operator at the manual exchange answers the call. Relay 805, upon energizing, at armature 823 prepares an energizing circuit for relay 803; at armature 824 opens the circuit of the bridged high-resistance relay 806; and at armature 825 completes a circuit for energizing relay 716. Relay 716 at armature 750 completes the previously-traced locking circuit for relay 713 before the slow-to-operate relay 711 deenergizes. When the manual operator at the manual office answers the incoming call, ground is connected to conductor 840, thereby closing a circuit extending by way of the normally closed springs controlled by armature 816, armature 823, and through the winding of relay 803 to battery for energizing the latter relay. Relay 803 at armature 816 completes a locking circuit for itself and also completes, at armature 817, the locking circuit for relay 716. At armature 814 relay 803 opens the circuit of relay 802 and prepares a point in the talking circuit between the subscriber S^2 and the manual operator. A short period thereafter, relay 802 deenergizes, and at armature 813 completes the talking circuit over the heavy talking conductors. The calling subscriber S^2 informs the manual operator of the subscriber desired, and the manual operator completes the connection in the well-known manner.

It will now be assumed that the trunk conductors 840 and 841 extend to an automatic exchange and, therefore, the operation of the switch-through relay 713 completes a circuit from ground over the short circuit of relay 802, normally closed springs controlled by armature 814, and from thence over the calling subscriber's loop circuit by way of conductors 754 and 766, winding of relay 801, resting contact of armature 813 and said ar-

mature, and over conductor 841 through the winding of the line relay in the incoming lineswitch to negative battery. The line relay of the incoming lineswitch in the automatic exchange operates in the well-known manner to seize an idle trunk at which time dial tone is transmitted back over conductors 840 and 841 to the calling subscriber. In addition, ground is connected to trunk conductor 840, thereby causing the energization of relay 803 which now energizes and causes the energization of relay 716 over circuits previously traced. Since relay 802 is not operated on calls to automatic exchanges, a direct metallic loop circuit is completed over conductor 840, armature 814 and its working contact, conductor 754 over the previously-traced subscriber's loop circuit to conductor 766, through the winding of relay 801, resting contact of armature 813 and said armature, and over the trunk conductor 841 to the main exchange. In response to the receipt of dial tone, subscriber S^2 dials the telephone number of the desired automatic subscriber, whereupon the switches in the automatic exchange are operated in the well-known manner to complete the desired connection. Relay 801 intermittently operates, but since relay 805 is slow-to-release on account of the copper sleeve around its core, said relay is maintained energized throughout the impulsive period. When the called subscriber answers, talking battery is fed to both the calling and called subscribers from the main exchange. When the subscribers hang up the circuit through relay 801 is opened and said relay at armature 810 opens the circuit of relay 805, and the latter relay, upon deenergizing, at armature 823 opens the circuit of relay 803. Relay 803 after an interval deenergizes and, at armature 817 opens the locking circuit of relay 716 which now deenergizes and opens the locking circuit of switch-through relay 713. Relay 713 deenergizes and the trunk finder is placed in condition to receive another outgoing trunk call as soon as relay 709 deenergizes when the last trunk in the exchange has been taken into use.

Subscriber S' may originate an outgoing call in the same manner as described for subscriber S^2 and subscriber S' may answer an incoming trunk call in the manner similar to that described for subscriber S' , and since the equipment and operation are somewhat similar, it is believed that a detailed description of such operations may be clearly understood without describing the same in detail.

Holding trunk circuits

In order to describe how subscribers equipped with sub-bases, such as SB, can hold a trunk call while either making or answering a local call, it will first be assumed that subscriber S' has answered an incoming trunk call and that the substation circuit of S' is,

therefore, connected to the trunk circuit by the operation of the answer key. It will further be assumed that during the time subscriber S' is conversing over the trunk circuit, that another local subscriber calls subscriber S' over one of the finder connector links and, therefore, operates the ringer bells RB associated with the line of subscriber S' . Since there are no multiple connections between the local finder and the trunk finder for guarding the local subscriber against intrusion when such local subscriber is engaged in a trunk call, the connector switch is operated to cause the operation of the ringer bells RB in the same manner as previously described. In response to the ringer bells, subscriber S' informs the main-exchange subscriber to wait for a short period of time and then releases the answer key, whereupon the bar 161 is operated to the position shown in the drawings, thereby releasing springs 151 and 156, while springs 152 and 155 are maintained locked in operated position by the bar 160. In response to the restoration of springs 151 and 156, the subscriber's substation circuit is directly connected across the local line conductors 131 and 132 to cause the operation of the ring-cut-off relay in the connector and to complete the talking circuit between the calling local subscriber and subscriber S' . As soon as the answer key was restored to its normal position, a holding circuit was closed over the talking conductors 171 and 172 as follows: conductor 171, locking spring 152, spring 154, springs 157 and 158 which close before spring 158 is disengaged from spring 156, to conductor 172. Subscriber S' may return to the trunk connection by operating either the "OUT" or the "ANS" key. The bar 161 is thereupon moved in a horizontal direction and again completes the connection between the trunk circuit and the substation circuit. The operation of either key automatically releases the local connection.

In case subscriber S' desires to originate a local connection and still maintain the connection over the trunk circuit, the main exchange subscriber will again be told to wait awhile and then subscriber S' restores the operated key to normal position. In response thereto, a circuit may now be traced from common line relay 117 by way of armature 114, conductor 131, resting contact of spring 156 and said spring, conductor 121, push-button springs 150, conductor 101 over the substation circuit to conductor 102, spring 151 and its resting contact, conductor 132, armature 116 and through the upper winding of two-step cut-off relay 213 to battery. Two-step relay 113 operates only in its first step to operate armature 115 to connect negative battery calling potential over conductor 111 to the banks of the local finders. Line relay 117, upon energizing over the above-traced circuit at armature 118 grounds the

common start conductor 9, whereupon an idle local finder connector link is taken into use. When the finder finds line S', subscriber S' dials the number of the desired local subscriber in response to the receipt of 5 dial-tone, the connector signals the called subscriber in the same manner as previously described. When the called subscriber answers and subscriber S' receives the desired information, the local connection may be released by subscriber S' operating either one of the keys to again connect the subscriber's 10 substation circuit to the held trunk circuit.

It will now be assumed that subscriber S² is engaged in a trunk call and that in response 15 to the operation of the incoming trunk signals subscriber S² desires to answer this second connection trunk call and at the same time maintain connection with the first trunk call. The subscriber, therefore, tells 20 the main-exchange subscriber on the first trunk to wait and then operates the "HOLD" key. A circuit may now be traced from ground by way of holding springs 259 and through the winding of relay 280 to battery. 25 At armature 284, relay 280 completes an energizing circuit for slow-to-operate relay 283 and the latter relay, upon energizing, at armature 292 completes a holding circuit for the first trunk extending from conductor 271, 30 armature 292, working contact of armature 297 and said armature to conductor 272. The first trunk circuit is held over this circuit until the hold key is released. At armature 290, relay 283 prepares a point in the transfer circuit to be subsequently described, and at armatures 291 and 292 disconnects the subscriber's substation circuit from conductors 271 and 272 at their resting contacts, and at 35 their working contacts connects the substation circuit across the conductors 294 and 296. A circuit may now be traced from ground through the common incoming line relay 261, armature 286, working contact of 40 armature 291 and said armature over the substation circuit to armature 293 and its working contact, armature 288 and its resting contact through the upper winding of two-step cut-off relay 282 to battery. Cut-off 45 relay 282 is energized in only its first step to close armature 287 to apply negative battery calling potential to conductor 295 which terminates in the set of bank contacts accessible to the incoming test wipers 703 of the 50 trunk finders. At armature 263, common incoming line relay 261 grounds the common incoming start conductor 165 to start the trunk finder, which is associated with the trunk line having the incoming call, in search 55 of the marked potential. The trunk finder will be operated in the same manner as previously described until the test wiper 703 of such finder encounters the bank contact terminating in conductor 295. In response 60 thereto, the test relay in the trunk finder oper-

ates and stops the wipers of the trunk finder in engagement with their twenty-third set of bank contacts. The various relays in the trunk finder are operated in the same manner as described for an incoming call and 70 the two-step cut-off relay 282 is energized in series with the test relay of the trunk finder to operate through its second step to disconnect the common line relay 261 at armature 286 and to disconnect the upper winding of 75 relay 282 from talking conductor 296 at armature 288 and its resting contact and at its working contact prepares a holding circuit over the second trunk conductors 294 and 296. The subscriber S² may now converse with the 80 calling subscriber over the second trunk line comprising conductors 294 and 296 which terminate in the twenty-third contacts in the upper and lower set of bank contacts accessible to wipers, such as 701 and 706, of the 85 trunk finder. Subscriber S² may hold the second trunk and return to the first trunk by returning the hold key to its normal position. In response thereto, springs 259 open the circuit of relay 280 which now deenergizes and 90 opens the circuit of relay 283. Relay 283 after an interval deenergizes, and at the make-before-break springs controlled by armature 291 completes a holding circuit for the second trunk extending from conductor 95 294, normally closed springs controlled by armature 291, armature 285, working contact of armature 288 and said armature to conductor 296. At the resting contacts of armatures 291 and 293, the first trunk comprising conductors 271 and 272 are again connected to the substation circuit, while at armature 292 the hold circuit across the first trunk line is opened. The subscriber may, as often as desired, switch from one trunk to the other at 100 will. With the aid of the above-traced holding circuits, a subscriber such as S² may originate an outgoing local call or may answer an incoming local call in the same manner as described for subscriber S' by maintaining 105 the hold key in operated position, while restoring the other key to normal. In response to the restoration of the "OUT" or "ANS" key, the bar 261 is returned to its normal position, thereby connecting the substation circuit across the local line circuit comprising 110 conductors 231 and 232. The common line relay 217 and individual two-step relay 218 and the local finder-connector link operates in the same manner as previously described 115 to complete the calls to or from the local line circuit comprising the conductors 231 and 232. The subscriber S² may at her option return to either the first or the second held trunk. The position of the hold key always 120 designates to the local subscriber which trunk call, first or second, the subscriber was last connected to, that is, if the hold key is operated, the subscriber was last connected to the second trunk line, while the first trunk 125

line was being held. In case subscriber S^2 desires to return first to the first trunk connection, the subscriber will release the hold key and operate either the "ANS" or "OUT" key, thereby deenergizing relays 280 and 283, whereupon the subscriber is connected to the first trunk, while the second trunk is held over the previously-traced holding circuit. In case subscriber S^2 desires to return to the second trunk connection after the previously-mentioned local connection, the subscriber would operate either the "OUT" or "ANS" key and maintain the "HOLD" key in operated position. The substation circuit will, therefore, be connected to the second trunk line.

In case the subscriber desires to release the trunk connection over either trunk circuit and maintain the other trunk circuit, such subscriber will operate the push-button 250 when the substation circuit is connected thereto to open the loop circuit through the substation circuit to release the trunk finder by deenergizing relay 801 in Fig. 8. After the release of one of the trunk circuits in this case assuming it to be the first trunk circuit, a new holding circuit is provided for the second trunk circuit in case the subscriber desires to answer or complete another local connection. This holding circuit extends by way of conductor 294, working contact of armature 291, springs 252 in operated position, springs 254, springs 257 and 258, armature 292 and its working contact to conductor 296. When the subscriber S^2 replaces the handset on the cradle, the keys are all automatically returned to their normal positions and the bars 260 and 261 are also returned to their normal positions causing the release of the spring assemblies in the sub-base and the release of relays 280 and 283. The deenergization of relay 283 will operate armatures 292 to open the holding circuit for the first trunk, the springs 251, 256, 253, and 253 operate and open any established hold circuits, and slow-to-operate relay 281 is energized over the following circuit: from ground through springs 253 which are operated when the handset is replaced on the cradle, armature 289 and through the winding of relay 281 to battery. At armature 285, relay 281 opens the holding circuit across the second trunk, whereupon if any of the trunk circuits are being held, such trunk circuits will be released in response to the replacement of the handset on the cradle.

Transfer circuits

It will now be assumed that subscriber S^2 is connected in a trunk call to the main exchange and that the subscriber in the main exchange desires to converse with another local subscriber, for example subscriber S' , Fig. 2. It will further be assumed that

subscriber S^2 is connected to the first trunk over conductors 271 and 272. In order to transfer the trunk call to subscriber S' , subscriber S^2 releases the operated key, thereby establishing a holding circuit for the first trunk as previously traced, and connects the substation circuit to the local line conductors 231 and 232, whereupon the common line relay 217, the cut-off relay 213, and an idle finder-connector link is operated in the same manner as previously described. When subscriber S^2 hears the well-known dial tone, subscriber S^2 will dial the local number 42 assigned to the line of subscriber S' , whereupon the connector in the finder connector link is operated into engagement with the local line circuit of subscriber S' . The connector wipers 401 to 406, inclusive, are therefore operated in response to the digits 4 and 2 into engagement with their sixteenth bank contact. If the line of subscriber S' is not engaged in a local connection, the subscriber is signalled in the same manner as previously described, and when subscriber S' answers, subscriber S^2 will inform subscriber S' that such subscriber is wanted on a trunk connection. In order to pick-up the trunk connection, subscriber S' will operate the "ANS" key without replacing the handset on the cradle. The spring assemblies shown in SB, Fig. 1, are operated in the manner previously described to complete a circuit for relay 141, common line relay 161 and two-step relay 140 as previously described. In response to the operation of relay 141, a circuit may now be traced for energizing two-step relay 140 through its second step as follows: from ground by way of armature 732, armature 742 and its resting contact, armature 728 and its working contact, wiper 703 in engagement with the contact terminating conductor 266 and said conductor, working contact of armature 248 and said armature, conductor 268, wiper 302, armature 342, upper winding of relay 313, conductor 364, wiper 402, conductor 166, working contact of armature 148 and said armature, armature 144 and through the lower winding of two-step relay 140 to battery. Relay 313 is energized in series with the two-step relay 140, and at armature 338 completes a locking circuit for itself extending by way of armature 348 to grounded conductor 367. At armature 336, relay 313 grounds conductor 365; at armature 337 grounds conductor 364 for maintaining the two-step relay 140 in operated position, at armature 339 short circuits the upper winding of relay 313 and grounds wiper 302 to maintain the cut-off relay 240 in energized position and to connect ground to conductor 266 by way of conductor 268 and armature 248 in order to prevent the operation of the test relay 712 in the trunk finder. At armature 340, ground is removed from conductor 358 and connected to conductor 130.

359, thereby closing a circuit for energizing relay 607 in the transfer sequence switch shown in Fig. 6. Relay 606 first operates its armature 613 to close a circuit for the motor magnet 604 in case the test wiper 603 is in engagement with a trunk conductor 358 having ground connected thereto. At armature 612 relay 607 closes a circuit for relay 606 which is effective only in case wiper 603 is in engagement with a conductor 358 having no ground connection. At armature 611 relay 607 prepares a point in the circuit for the transfer relay 715 in the trunk finder, Fig. 7. In case wiper 603 is in engagement with a grounded contact, relay 606 is short circuited and a circuit may be traced from wiper 603 by way of armature 613, normally closed spring controlled by armature 610, interrupter spring 605 of the motor magnet 604, and through the winding of magnet 604 to battery. Motor magnet 604 operates in the manner of a buzzer to step the wipers 601 to 603, inclusive, until the wiper 603 encounters the bank contact terminating the conductor 358 from which ground has been removed by the operation of the transfer relay 313 in the local finder. The wipers of the transfer sequence switch will, therefore, come to rest upon selecting the aforementioned local finder. The circuit for energizing relay 606 is now effective and extends by way of armature 612, winding of relay 606, normally closed springs controlled by armature 610, interrupter springs 605, motor magnet 604 to battery. Due to the high resistance in the winding of relay 606, motor magnet 604 does not energize and relay 606 at armature 610 completes a locking circuit for itself. At armature 609, relay 606 connects negative battery transfer potential to the thirteenth bank contact accessible to the transfer test wiper 704 in the trunk finder over the following circuit: negative battery, resistance and armature 609, wiper 602, conductor 361, upper winding of relay 315, conductor 370, wiper 405, conductor 469 to Fig. 7. At armature 608, relay 606 completes a circuit for energizing the transfer relay 715 in the trunk finder as follows: from ground by way of armature 611, armature 608, wiper 601, conductor 356, wiper 305, conductor 354 to Fig. 7, wiper 705, normally closed springs controlled by armature 738, armature 748 and through the winding of transfer relay 715 to battery. Relay 715, upon energizing, at armature 743 opens the locking circuit of switch-through relay 731; at armature 742 and its working contact prepares the test circuit extending to the transfer test wiper 704, and at armature 744 prepares a circuit for energizing the start relay 711. Relay 713, upon deenergizing, at armature 732 removes ground from the upper winding of relay 712; at armature 733 opens a further point in its own locking circuit, at armature 734 completes a circuit for energizing relay 714, and at armature 735 completes a circuit for energizing start relay 711 as follows: ground at armature 750, armature 744, armature 735 and its resting contact and through the winding of start relay 711 to battery. Start relay 711 at armature 729 again completes the stepping circuit for the stepping relay 708 and motor magnet 707 to cause the trunk finder to hunt for the transfer potential applied to the contacts accessible to wiper 704, and at armatures 727 and 728 prepares the test circuit for test relay 712. The wipers of the trunk finder are again rotated step-by-step until test wiper 704 encounters the bank contact terminating in conductor 469 upon which the transfer potential has been applied at which time a circuit may be traced from grounded armature 727, through the upper operating winding of test relay 712, armature 742 and its working contact, transfer test wiper 704 to the contact terminating in conductor 469. Test relay 712 energizes from the transfer potential over the above-traced circuit and at armature 730 opens the stepping circuit and again energizes switch-through relay 713. Relay 714, upon energizing, at armature 737 closes a shunt circuit around armature 741 which closed a holding circuit over the trunk as follows: conductor 840, armature 814 and its working contact, conductor 754, armature 741 or armature 737, armature 746, conductor 755, relay 801, and through the resting contact of armature 813 and said armature to trunk conductor 841. Relay 801 is maintained energized over this holding circuit to prevent the release of the connection when relay 713 deenergizes as previously described. At armature 738, relay 714 opens the original energizing circuit of relay 715, but the latter relay and relay 714 are maintained energized for a short interval from the grounded armature 734 of relay 713 which has not yet energized. At armature 739 relay 714 prepares a temporary locking circuit for relay 713, and at armature 740 energizes relay 710 if the same is not already operated.

Returning now to the local finder-connector link and at the time when relay 315 energizes in series with test relay 712 of the trunk circuit, relay 315 at armature 344 completes a locking circuit for itself to grounded-hold conductor 367; at armature 358 opens the locking circuit of relay 313 which deenergizes after an interval because of the short circuit around its upper winding, and at armature 345 replaces the ground which will be removed by armature 339 when relay 313 deenergizes. At armature 347, relay 315 grounds the generator start conductor 360 with the result that relay 615 in Fig. 6 is operated to initiate the operation of the busy-tone relay and the ringer-interrupter relays

in the manner previously described. At armature 356, relay 315 closes a signalling circuit for transmitting the busy-tone to subscriber S^2 to inform such subscriber that the transfer has taken place. This circuit may be traced from busy-tone conductor 459, armature 346, conductor 374 and from thence over the heavy talking conductors to the local circuit of subscriber S^2 . Relay 313, upon de-energizing, at armature 340 removes ground from conductor 359, thereupon deenergizing relay 607 which in turn causes the deenergization of relay 606. The transfer sequence switch TSS is now in normal position and may be used when other calls are to be transferred. When subscriber S^2 hears the busy tone indicating the transfer of a call, such subscriber will replace the handset on the cradle in case the subscriber is not holding another trunk connection.

Returning now to the trunk finder and at the time switch-through relay 713 energizes to switch subscriber S' through to the trunk and also opens the locking circuits of relays 715 and 714 at armature 734, relay 715 will de-energize before slow-to-release relay 715 in order to maintain the switch-through relay 713 in energized position. During the time relay 714 is energized and relay 715 is de-energized, relay 713 is locked up from ground by way of armature 750 and armature 739 and its working contact. When relay 714 deenergizes shortly thereafter, the locking circuit from grounded armature 750 for relay 713 is maintained at the make-before break springs controlled by armature 739 and armature 743. In addition, at armature 737, relay 714 opens the holding circuit for relay 801 and the latter relay is now maintained energized over the subscriber's loop circuit. The trunk finder is now connected to the line of subscriber S' and the subscriber S' and the main-exchange subscriber may converse as desired.

Subscriber S' can also transfer a trunk call, and for this purpose it will be assumed that subscriber S' desires to transfer a trunk call to subscriber S^2 . Subscriber S' releases the operated key and calls subscriber S^2 over the local switch train including a finder connector link, such as shown in Figs. 3 and 4. Since this transfer is somewhat similar to the transfer just previously described, a brief description of the transfer circuits alone will be described. In this case since the trunk line circuit of subscriber S' is connected with the trunk to be transferred, the trunk finder wipers are in engagement with their thirteenth bank contacts. Subscriber S' holds the trunk by releasing the operated key, thereby causing a local finder connector link to establish a connection with the local line circuit of subscriber S' . Subscriber S' then operates the connector to signal subscriber S^2 in the same manner as previously de-

scribed. When subscriber S^2 answers the call, subscriber S' tells subscriber S^2 to pick up the trunk call which subscriber S^2 does by operating the "ANS" key. Relay 241 is operated responsive to the operation of the "ANS" key and cut-off relay 240 is first operated in its first step and then operated in series with relay 313 (Fig. 3) over the following circuit: from ground by way of armature 732, armature 742 and its resting contact, armature 723 and its working contact, incoming test wiper 703, conductor 166, working contact of armature 148 and said armature, conductor 168, wiper 302, armature 342, upper winding of relay 313, conductor 364, wiper 402, conductor 266, working contact of armature 248, armature 244 and through the lower winding of relay 240 to battery. The transfer sequence switch TSS, Fig. 6, is again operated in response to the energization of relay 313 to complete a circuit for energizing the transfer relay 715 in the trunk circuit. This circuit may be traced from ground at armature 611 (Fig. 6), armature 608, wiper 601, conductor 356, wiper 305, conductor 353, wiper 705, normally closed springs controlled by armature 738, armature 748 and through the winding of relay 715 to battery. The energization of relay 715 causes the trunk finder to hunt for the transfer potential in the same manner as previously described. The line of subscriber S^2 is made busy to other local connectors and finders from grounded armature 337, while the line of subscriber S' is made busy to the other trunk finders from ground at armatures 339 and 342. When the trunk finder finds the transfer potential, relay 315 in the local finder connector link and test relay 712 in the trunk finder energize in series from ground at armature 727 through the upper operating winding of test relay 712, armature 742 and its working contact transfer test wiper 704, conductor 470, wiper 405, conductor 370, through the upper winding of relay 315, conductor 361, wiper 602, through armature 609 and the resistance to battery. The trunk finder then switches through in the same manner as previously described to connect the line of subscriber S^2 to the trunk circuit. Subscriber S' is informed of the transfer by the receipt of busy-tone and therefore releases from the connection.

Subscribers, such as subscriber S^2 as previously described, can answer a second incoming trunk call, and in case some other subscriber is desired in this trunk call, subscriber S^2 can transfer such trunk call to the desired subscriber. For example, when subscriber S^2 answers a second trunk call and is informed by the main-exchange subscriber that subscriber S' is desired in the trunk connection, subscriber S^2 will, therefore, transfer this section trunk call to subscriber S' in a

manner somewhat similar to that previously described. In this case since the trunk connection to be transferred has been received by subscriber S² over the second trunk-line circuit or over conductors 294 and 296, the 5 trunk-finder wipers are therefore in engagement with their twenty-third bank contacts. When subscriber S² releases the operated key, the holding circuit for the second trunk connection is established as previously described, 10 it being understood, of course, that the previously-described holding circuit for the trunk call or the first trunk connection was completed when subscriber S² answered the 15 second trunk call. Subscriber S² now calls the local line of subscriber S' over the local switch train and when subscriber S' answers and operates her "ANS" key, the transfer of the trunk connection takes place in a manner 20 somewhat similar to that previously described. In this case, however, since relay 283 in the trunk-line circuit of subscriber S² is operated, the calling potential for the local finder will extend from the lower winding of 25 cut-off relay 213, armature 215, working contact of armature 290 and said armature, conductor 212 which terminates in the twenty-third bank contact accessible to the test wiper 303 of a local finder. The wipers of the local 30 finder are therefore operated into engagement with their twenty-third bank contacts to complete connections to the local line circuit of subscriber S'. It will be noted in Fig. 3 that the twenty-third bank contacts 35 accessible to wipers 301, 304, and 306 are multiplied with the eighteenth bank contacts associated therewith. The transfer circuit for energizing relay 313 in the local finder extends from ground at armature 732, Fig. 40 7, armature 742 and its resting contact, armature 723 and its working contact, wiper 703 in engagement with the twenty-third bank contact, conductor 295, wiper 302, armature 342, upper winding of relay 313, conductor 364, wiper 402, conductor 166, armature 148, armature 144, and through the 45 lower winding of two-step cut-off relay 140 to battery. The circuit for energizing the transfer relay 715 in the trunk finder extends 50 from ground at armature 611, Fig. 6, armature 608, wiper 601, wiper 305, conductor 355, wiper 705, normally closed springs controlled by armature 738, armature 748, and through the winding of transfer relay 715 to battery. The circuit for energizing 55 relay 315 in the local finder and test relay 712 in the trunk finder in series is the same as that previously described in transferring the first call to subscriber S'. The local finder connector link and the trunk finder operate in the same manner as previously described to connect the trunk connection to the trunk-line circuit of subscriber S'.

Restricted service

In some instances in privately-owned telephone exchanges, it is customary to allow only certain subscribers' lines to originate outgoing trunk calls, while other subscribers' 70 lines are restricted from making such calls. In order to explain this type of service it will be assumed that subscriber S' is restricted against making outgoing calls, but may answer incoming calls. In this case, when subscriber S' is restricted against making 75 outgoing calls, conductor 104 instead of being connected to terminal 103 is jumpered to terminal 105. In case subscriber S' should operate the "OUT" key, a circuit may be 80 traced for operating the high-resistance restricted-service relay 223 as follows: from ground through the winding of relay 223, common conductor 107, terminal 105, conductor 104, resting contact of armature 146 85 and said armature, armature 142, springs 155, through the substation circuit to conductor 101, push-button springs 150, springs 156 and 158, armature 145 and through the upper winding of two-step relay 140 to battery. Due to the high resistance winding of 90 relay 223, two-step relay 140 is not operated over the above-traced circuit, but relay 223 energizes and at armature 225 grounds conductor 227 for initiating the operation of the busy-tone relays 616, 617, and 618 to complete 95 a busy-signalling circuit for the calling subscriber's line. This circuit may be traced from the interrupted springs 630 and 629 to conductor 226, armature 224, to common conductor 107 and thence over the calling substation circuit to battery at the cut-off relay.

Conference calling

In order to describe this feature, it will 105 be assumed that a plurality of local subscribers have been informed that a conference is desired, the subscribers all, therefore, call a certain number set aside for conference calls. The local finders and connectors are operated 110 in the same manner as previously described, the wipers of the connectors all being operated into engagement with their thirteenth bank contacts. The thirteenth bank contacts 115 accessible to wipers 401 and 406 in all of the connector banks are multiplied together and provide a common talking circuit for all of the subscribers which have operated connector switches to this position. The thirteenth bank contact accessible to the test wiper 403 of all of the connectors are not multiplied and, therefore, each connector switch has an individual lead such as lead 465 for connecting switch-through battery potential to the thirteenth bank contacts. Since the thirteenth bank contacts accessible to the test wiper 403 of the connectors are not multiplied, no 120 busy circuits are provided for preventing connection therewith, with the result that there 125 130

may be as many connections established to the conference trunk comprising conductors 462 and 472 as there are local finder connector links.

Code call

5 In case a local subscriber calls another local subscriber and his location is not known, the calling subscriber may operate the code-call switch shown in Fig. 5 to signal the called 10 subscriber over the code-call system. In this case, the calling subscriber will first release from the connection to the called subscriber's line and will then dial the digit assigned to the code-called number, in this case the subscriber 15 after removing his handset from the cradle will dial the digit 2. In case the code-call switch is not busy there will be a negative battery potential on conductor 464 extending through the winding of start relay 509. The 20 switching relay 414 in the connector will switch through and at armature 442 complete a circuit for energizing the ring-cut-off relay 411 in series with relay 516 as follows: from ground by way of winding of relay 516, conductor 461, wiper 401, armature 442, armature 430 and its resting contact and through the lower winding of relay 411 to battery. Relay 411 operates and closes a locking circuit for itself at armature 431. At armature 25 443 switching relay 414 closes the following circuit for energizing the start relay 509 in the code-call switch: from ground at armature 443, wiper 403, conductor 464, armature 30 534 and its resting contact, armature 523 and its resting contact and through the winding of slow-to-operate start relay 509. Relay 516, upon energizing, at armature 536 applies a marking potential, in this case ground, 35 through relay 311 of the local finder to the bank contacts accessible to test wiper 502 of the code-call switch. This circuit may be traced from ground at armature 536, conductor 357, lower winding of relay 311, wiper 45 504, over any one of the conductors, such as conductors 350 to 352, inclusive, dependent upon the subscriber initiating the call, and to the bank contacts accessible to the test wiper 502 of the code-call switch. At armature 520, 50 start relay 509 completes a circuit for the polarizing winding of the three-pole test relay 508; at armature 519 prepares a point in the test circuit through the upper operating winding of relay 508, and at armature 521 55 completes the stepping circuit. Stepping relay 507 is energized from ground by way of armature 521, armature 518 and its resting contact, winding of relay 507, and through the interrupter spring 506 of motor magnet 60 505 to battery. Stepping relay 507 energizes and at armature 517 completes an obvious circuit for energizing the motor magnet 505 which now energizes, and at interrupter springs 506 interrupts the circuit of stepping 65 relay 507. Stepping relay 507 deenergizes,

and at armature 517 opens the circuit of stepping magnet 505 which now deenergizes, steps the wipers 501 to 504, inclusive, and reestablishes the circuit for stepping relay 507. This interaction of the stepping relay 507 70 and motor magnet 505 continues until the stepping circuit is opened at armature 518 by the operation of the test relay 508 which takes place when test wiper 502 encounters ground potential. The circuit for energizing 75 the three-pole test relay 508 is as follows: from ground by way of armature 536, conductor 357, lower winding of relay 311, wiper 304, one of the conductors extending to the bank contacts accessible to wiper 502, armature 519, and through the upper operating winding of relay 508 to battery. At armature 518, relay 508 opens the stepping circuit to stop the code-call finder wipers and to complete a circuit for energizing switch-through 80 relay 510. At armature 523 and its resting contact, relay 510 opens the circuit of slow-to-operate start relay 509, and at its working contact connects ground to conductor 464 for marking this code-call switch busy in the 85 banks of the local finder. At armature 524, relay 510 connects ground to wiper 503 to busy the calling local line. At armatures 522 and 525, relay 510 completes a circuit for energizing the line relay 511 over the call subscriber's loop as follows: ground through the lower winding of line relay 511, armature 525, wiper 504, over conductor 232 in case subscriber S² is the calling subscriber, resting 90 contact and spring 251 and said spring, conductor 202, substation loop circuit to conductor 201, springs 250, conductor 221, spring 256 and its resting contact, conductor 231, wiper 501, armature 522, and through the upper winding of line relay 511 to battery. 95

When the code-call relay 311 operates in series with the test relay 508 of the code-call switch, relay 311 at armatures 333 and 326 opened the circuit extending to the line relay 407 of the local connector. Line relay 407 deenergizes and causes the release of the finder connector link in the same manner as previously described. The release of the connector to normal opens the circuit of relay 516 which removes ground from conductor 357 to 100 deenergize the code-call relay 311.

Line relay 511, upon energizing over the calling subscriber's loop circuit, at armature 527 closes a circuit for energizing the slow-to-release release relay 512. At armature 528, 105 relay 512 prepares an operating circuit for slow-to-release series relay 513; at armature 529 closes a holding circuit for relay 510; at armature 531 completes a circuit for operating the differentially wound dial-tone relay 545 which now operates in the manner of a buzzer to intermittently open and close its contact springs 546; and at armature 530 completes a circuit for transmitting dial tone to 110 the calling subscriber. This dial-tone cir- 115

cuit extends from battery and resistance connected to the vibrating armature 546, common conductor 547, armature 530, armature 535, the dial-tone condenser, conductor 471, 5 the talking condenser to the lower winding of line relay 512 and to armature 525, and from thence over the previously-traced circuit through the calling subscriber's substation circuit back to the upper winding of line 10 relay 511. In response to the receipt of dial-tone, which informs the subscriber that the code-call switch is now ready to receive dial impulses, the calling subscriber will thereafter dial the digits of the code-call number 15 assigned to the desired subscriber. Each subscriber which may be signalled over the code-call signalling circuit is assigned a code-call ring comprising a series of short or long rings or a combination of both. Assuming that the 20 code of the desired called subscriber is one short and one long ring, the calling subscriber will operate the calling device CD to send out first a short series of impulses, in this case the digit 1 or 2, and will then operate the calling device to send out a longer series of impulses, in this case 9 or 10 impulses. In response to the first series of impulses, the line relay 511 is deenergized a correspondingly number of times to operate slow-to-release 25 series relay 528 upon the first deenergization of line relay 511, and to operate the slow-to-release ring control relay 514 in response to the first energization of line relay 511. Relays 512, 513, and 514 are each provided with 30 a copper sleeve around the magnet core in order to make these relays slow-to-release. The release relay 512 will therefore be maintained in energized position throughout the dialling period, series relay 513 will therefore 35 energize at the start of the dialling period and deenergize shortly thereafter, while the relay 514 will be maintained energized a short interval of time after series relay 513 deenergizes. At armature 533 a circuit is completed 40 for energizing ringing relay 540, and the latter relay at armature 541 completes the code-call signalling circuit. This circuit may be traced from a source of commercial power over conductor 543, armature 541, conductor 45 542 to the code-call signals which are located at different points served by this telephone system back through conductor 544 to the source of commercial power. Since the first digit dialled comprises only a few impulses 55 relay 514 will be held in operated position for only a short period of time and therefore relay 540 will likewise be held operated for a short period of time to operate the code-call signals in accordance with a short ring. The 60 next or second digit dialled by the calling subscriber comprises a much greater number of impulses and therefore the relay 514 is held in operated position for a considerable longer period. Relay 540 is therefore likewise energized for a longer period of time, and there- 65 fore in response to the second digit, the code-call signals are operated for a long ring. The calling subscriber will continue to operate the code-call signals until the desired subscriber answers. The called subscriber in response 70 to hearing his code ring will answer this call by removing the handset from the cradle of the nearest telephone and dial the code-call answer number. The code-call answer number, in this case, is the digit 1. In response 75 to the removal of the handset from the cradle the finder of a local finder finds the call just initiated and the connector associated therewith is operated into engagement with the first bank contact in response to the digit 1 in 80 the same manner as previously described. When series relay 409 in the operated connector deenergizes, a circuit may be traced for energizing the switch-through relay 414 as follows: from ground by way of armature 85 418, armature 433 and its resting contact, lower winding of switching relay 414, resting contact of armature 422 and said armature, armature 425, normally closed springs controlled by armature 443, wiper 403, conductor 90 463, and through the resistance to negative battery. At armature 443 switching relay 414 grounds conductor 463 to busy the code-call answer circuit, and at armatures 442 and 452 completes a circuit for energizing ring- 95 cut-off relay 411 in series with the bridged relay 515. This circuit may be traced from the common ringing conductor 457, resting contact of armature 432 and said armature, armature 452, wiper 406, conductor 471, winding 100 of relay 515, conductor 460, wiper 401, armature 442, armature 430 and its resting contact and through the lower winding of ring-cut-off relay 411 to battery. Relays 515 and 411 are energized over this circuit in response 105 to either ringing current or ground applied at armature 633 by the ringing interrupter relay 620 in Fig. 6. Relay 515 at armature 535 disconnects dial tone from the calling subscriber and at armature 534 grounds conductor 464 to make this code-call switch busy to other connector switches. Ring-cut-off relay 411 upon energizing completes a locking circuit for itself at armature 431, and at armatures 430 and 432 complete the talking circuit 110 between the two subscribers. The talking circuit extends over the heavy talking conductors by way of conductors 231 and 232, wipers 501 and 504, armatures 522 and 525, conductors 460 and 471, wipers 401 and 406, armatures 442 and 452, armatures 430 and 432, conductors 362 and 375, armature 335, armatures 334 and 332, armatures 333 and 326, wipers 301 and 306 and from thence out over 115 the talking conductors of the subscriber's line which the called subscriber used in answering his code rings. Talking battery is fed to the calling subscriber, or subscriber S², through the windings of line relay 511, while the called subscriber is fed talking battery through the 120 125 130

windings of line relay 407 of the connector shown in Fig. 4.

When the calling subscriber replaces the handset after termination of conversation, line relay 511 deenergizes and at armature 527 opens the circuit of release relay 512. A circuit is completed for series relay 513 at this time, but the energization of series relay 513 is without effect because no circuit is completed for relay 514. After a short interval, relay 512 deenergizes and at armature 528 opens the circuit of relay 513; at armature 529 opens the circuit of relay 510; and at armatures 530 and 531 opens the circuit of dial tone relay 545 as well as opening a further point in the dial-tone circuit. When the called subscriber replaces his handset, line relay 407 deenergizes and releases the connector switch in the same manner as previously described. The finder connector link is therefore restored to its normal position and as a result thereof the bridge relay 515 in the code-call switch also deenergizes. The code-call switch is now in normal position and may be used in other calls.

Alarm signalling relays

The various types of switches are fused separately as indicated by the fuse shown in Fig. 3, Fig. 5, and Fig. 8. In case the fuse associated with the local finder connector links should blow, main battery will be connected to the upper winding of relay 311 which will energize and at armature 324 ground conductor 372 by way of armature 329 for energizing slow-to-operate alarm relay 650. In addition, in case the fuse associated with the code-call switch should blow, main battery would be connected to conductor 550 for also energizing the relay 650. In a similar manner, in case the fuse associated with the trunk circuits should blow, main battery will be connected through a resistance and the winding of relay 804 which energizes and at armature 815 grounds conductor 872 for completing an energizing circuit for relay 650. Relay 803 cannot energize because the battery feed thereto is opened by the blowing of the fuse. The energization of relay 650 at armature 660 closes a circuit over a pair of conductors 669 and 670 to operate an alarm circuit in the main exchange. At armature 656, relay 650 closes a circuit for operating the buzzer 655 and at armature 657 closes a circuit for opening the lamp 661. If for some reason the charging current extending over conductors 659 and 668 should be disconnected or the charge fuse blow, relay 653 will deenergize and complete a circuit for energizing relay 652. Relay 652 at armature 664, completes a circuit for operating the buzzer 655 by way of the key 654; at armature 665 completes a circuit for operating the lamp 663 and at armature 666 completes a circuit for operating the

alarm over conductors 669 and 670 in the main exchange.

In case the main battery fuse should blow, relay 651 normally bridged across the two poles of main battery will deenergize and at armature 662 closes a circuit over the conductors 669 and 670 for operating the alarm signal in the main exchange.

Having described the invention what is considered new and is desired to have protected by Letters Patent will be pointed out in the following claims:

What is claimed is:

1. In a telephone system, a local exchange and a distant exchange, a plurality of subscribers' lines in said local exchange, a plurality of trunk lines connecting said exchanges, incoming trunk signals common to all said trunk lines, means for operating all said signals responsive to an incoming trunk call on any one of said trunk lines, and means for automatically connecting the trunk line in use in the incoming call with a subscriber's line in response to such subscriber answering the call. 90

2. In a telephone system, a local exchange and a distant exchange, a plurality of subscribers' lines in said local exchange, a plurality of trunk lines connecting said exchanges, an answer key individual to each subscriber's line always operated by the subscriber in answering an incoming trunk call on any one of said trunk lines, and a step-by-step finder individual to each trunk line and operated responsive to the operation of an answer key to hunt for and connect the subscriber's line associated with the operated key with the trunk line in use in said incoming call. 100

3. In a telephone system, a local exchange and a distant exchange, a plurality of subscribers' lines in said local exchange, a plurality of two-way trunk lines connecting said exchanges, an answer key individual to each subscriber's line always operated by the subscriber in answering an incoming trunk call on any one of said trunk lines, an outgoing key individual to each subscriber's line always operated in originating an outgoing trunk call over any one of said trunk lines, and a step-by-step finder individual to each trunk line, one of said finders operated responsive to the operation of an answer key for connecting the trunk line in use in said incoming call with the subscriber's line associated with the operated answer key and one of said finders operated responsive to the operation of an outgoing key for connecting the first idle trunk line with the subscriber's line associated with the operated outgoing key. 110

4. In a telephone system, a local exchange and a main exchange, two-way trunk lines connecting said exchanges, finders having wipers in said local exchange terminating said trunk lines, local subscribers' lines accessible to the wipers of said finders, subscriber 120

130

- controlled means associated with each local line for marking the subscriber's line in the banks of the finders and for initiating the operation of a first idle one of said finders in response to originating an outgoing trunk call and in response to answering an incoming trunk call for initiating the operation of the finder in use on said incoming call, and means in said finders for thereafter operating the wipers to hunt and find the marked subscriber's line. 5
5. In a telephone system, subscribers' lines, a trunk finder in which said lines terminate, wipers on said finder having access to said lines, a trunk circuit for extending incoming and outgoing calls, means for operating said finder to connect said trunk circuit to one of said lines, keys at each of said subscribers' lines operated for initiating the operation of said finder when answering an incoming call or originating an outgoing call, and two different test circuits each leading through different wipers in said finder effective dependent upon whether a subscriber's line is originating a call or answering a call for controlling the extent of operation of said finder. 10
6. In a telephone system wherein a plurality of subscribers' lines are each provided with an answering key for answering trunk calls incoming over a plurality of trunk lines connected with a distant exchange, incoming trunk signals common to all said trunk lines, means for operating all said signals responsive to an incoming trunk call on any one of said trunk lines, a step-by-step finder associated with each trunk line, and means responsive to the operation of an answer key by any subscriber for operating the finder associated with the trunk line having the incoming call to hunt for the subscriber's line associated with the operated key and connect such subscriber's line to said trunk line. 15
7. In a telephone system, a private automatic exchange, a main exchange, two-way trunk lines connecting the main exchange with the private automatic exchange, a trunk finder terminating each trunk line in the private automatic exchange, subscribers' trunk-line circuits accessible to said finders, an answering and an outgoing key at each subscriber's substation associated with each subscriber's line circuit, means responsive to the operation of the answering key at any one of said subscribers' lines in response to an incoming call on one of said trunk lines for operating the trunk finder associated with said trunk line to find the subscriber's line associated with the operated key, and means responsive to the operation of the outgoing key at any one of said subscribers' lines for operating the trunk finder of the first idle trunk line to find the subscriber's line associated with the operated outgoing key. 20
8. In a telephone system, a local subscriber's line comprising a local line circuit, a trunk-line circuit and a substation circuit, trunk lines, means responsive to the removal of the receiver at the substation for connecting said substation circuit to said local line circuit, means for establishing a plurality of trunk connections between a plurality of said trunk lines and said trunk-line circuit, holding circuits for said trunk-line connections in said trunk-line circuit, and subscriber-controlled means for completing said holding circuits and for connecting said substation circuit to either trunk-line connection by way of said trunk-line circuit or to another subscriber's line by way of said local line circuit. 25
9. In a telephone system, a local subscriber's line comprising a local line circuit, a trunk-line circuit, and a substation circuit, trunk lines, means responsive to the removal of the receiver at the substation for connecting said substation circuit to said local line circuit, means for establishing a plurality of trunk connections between a plurality of said trunk lines and said trunk-line circuit, holding circuits for said trunk-line connections in said trunk-line circuit, subscriber controlled means for completing said holding circuits and for connecting said substation circuit to either trunk-line connection by way of said trunk-line circuit or to another subscriber's line by way of said local line circuit, and means responsive to the replacement of said receiver for releasing both trunk connections and the local connection. 30
10. In a telephone system, a local subscriber's line comprising a local line circuit, a trunk-line circuit, and a substation circuit, trunk lines, means responsive to the removal of the receiver at the substation for connecting said substation circuit to said local line circuit, means for establishing a plurality of trunk connections between a plurality of said trunk lines and said trunk-line circuit, holding circuits for said trunk-line connections in said trunk-line circuit, subscriber controlled means for completing said holding circuits and for connecting said substation circuit to either trunk-line connection by way of said trunk-line circuit or to another subscriber's line by way of said local line circuit, and a push-button individual to said subscriber when operated for releasing the trunk or local connection which is at the time connected to said substation circuit. 35
11. In a telephone system, a private automatic exchange and a main exchange, two-way trunk lines connecting said exchanges, private automatic exchange subscribers' lines accessible to each other and to said trunk lines, means for establishing connections between said trunk lines and said subscribers' lines, holding circuits for said trunk lines, subscriber-controlled means associated with each subscriber's line for completing said holding circuits on established trunk connections while completing other trunk and local 40

connections, and means for guarding said held trunk connections from intrusion.

12. In a telephone system, subscribers' lines, trunk lines, means for establishing and maintaining a plurality of trunk connections between a plurality of said trunk lines and one of said subscribers' lines, subscriber-controlled means for connecting the subscriber's substation circuit to either trunk connection at will while holding the other trunk connection, and means for guarding the held trunk connections from intrusion by other subscribers.

13. In a telephone system, local subscribers' lines, inter-exchange trunk lines, local connecting means and trunk connecting means, a local line circuit individual to each subscriber's line terminating in said local connecting means, a trunk-line circuit individual to each subscriber's line terminating in said trunk connecting means in a plurality of positions, a substation circuit individual to each subscriber's line normally connected to its local line circuit, means for establishing and maintaining a plurality of trunk connections to one of said subscriber's trunk-line circuits over a plurality of said trunk lines and a plurality of said positions in said trunk connecting means, and means for disconnecting the substation circuit from said local line circuit and for connecting said substation circuit to a desired one of said established trunk connections at the will of the subscriber.

14. In a telephone system, local subscribers' lines each having a trunk-line circuit individual thereto, a substation circuit individual to each subscriber's line and normally disconnected from its individual trunk line circuit, inter-exchange trunk lines, means for establishing a connection between a trunk line and one of said subscriber's trunk-line circuits, means in said trunk-line circuit for holding said first trunk-line connection, means for establishing a second trunk-line connection between a second trunk line and said trunk-line circuit, means in said trunk-line circuit for holding said second trunk-line connection, and means controlled at the will of said subscriber for establishing both said holding means and for connecting the individual substation circuit to said trunk-line connections or to a local connection as desired.

15. In a telephone system, a local subscriber's line comprising a substation circuit, a trunk-line circuit, a local line circuit and a spring assembly for connecting the substation circuit to either the trunk-line circuit or the local line circuit, trunk lines, means for establishing a plurality of trunk connections between a plurality of said trunk lines and said trunk-line circuit, a plurality of holding circuits for holding said trunk connections when said substation circuit is disconnected from such connections, the hold-

ing circuits for the first trunk connection including both said trunk-line circuit and said spring assembly in case the substation circuit is connected to said local line circuit and only the trunk-line circuit in case the substation circuit is connected to the second trunk connection, and the holding circuits for the second trunk connection including both the trunk-line circuit and the spring assembly in case the substation circuit is connected to the local line circuit and only the trunk-line circuit in case the substation circuit is connected to either the local line circuit or the first trunk connection.

16. In a telephone system, local subscribers' lines each comprising a local line circuit, a trunk-line circuit, a substation circuit, a spring assembly for connecting the substation circuit to either the trunk-line circuit or the local line circuit, and an answer key and an outgoing key for controlling said spring assembly, a plurality of two-way inter-exchange trunk lines, means responsive to the operation of an outgoing key at one of said subscribers' lines for operating said spring assembly and for connecting the subscriber's substation circuit to the first idle one of said trunk lines by way of the associated trunk-line circuit, means responsive to the operation of the answering key at said subscriber's line in response to an incoming call on any one of said trunk lines for operating said spring assembly and for connecting the subscriber's substation circuit to this trunk line by way of the subscriber's trunk-line circuit, and a hold key individual to said subscriber's line for controlling said trunk-line circuit to permit the answering of a second trunk connection while holding the first trunk connection and for controlling holding circuits to hold said trunk connections.

17. In a telephone system, a subscriber's line, sets of springs individual to said line, a single key controlled by said subscriber for controlling said springs, a plurality of trunk lines, means responsive to the operation of said key and springs by the subscriber for establishing a connection between said subscriber's line and any one of said trunk lines, means for automatically locking a certain set of said springs in response to their initial operation, a holding circuit including said certain set of locked springs for holding an established trunk connection, means responsive to the restoration of said key and all said springs except said locked set for establishing said holding circuit, and means for unlocking said certain set responsive to the replacement of the receiver by the subscriber.

18. In a telephone system, a subscriber's line, a pair of springs individual to said line and controlled by said subscriber, a plurality of trunk lines, means responsive to a call by said subscriber and the operation of said

5 springs for establishing a connection between said subscriber's line and any one of said trunk lines, means for locking said springs in operated position, a holding circuit including said springs for holding an established trunk connection, and means for establishing said holding circuit while completing a local connection to another subscriber's line.

10 19. In a telephone system, subscribers' lines, trunk lines, finders associated with said trunk lines, means for operating a finder to connect one of said trunk lines with one of said subscribers' lines, and subscriber-controlled means for re-actuating said finder to disconnect said trunk line from said subscriber's line and connect it with another subscriber's line.

20 20. In a telephone system, subscribers' lines, trunk lines, means for establishing and maintaining a plurality of trunk connections between a plurality of said trunk lines and one of said subscribers' lines, and means for holding and guarding said trunk connections while establishing a local connection between said subscriber's line and another local subscriber's line.

25 21. In a telephone system, subscribers' lines, trunk lines, means for establishing and maintaining a plurality of trunk connections between a plurality of said trunk lines and one of said subscribers' lines, means for holding and guarding said trunk connections while establishing a local connection between said subscriber's line and another local subscriber's line, and means for transferring either trunk connection to said other subscriber's line.

30 22. In a telephone system, subscribers' lines, trunk lines, means for establishing and maintaining a plurality of trunk connections between a plurality of said trunk lines and one of said subscribers' lines, means for holding and guarding said trunk connections while establishing a local connection between said subscriber's line and another local subscriber's line, means for transferring either trunk connection to said other subscriber's line, and means for thereafter preventing all subscribers' lines except said other subscriber's line from receiving said transferred trunk connection.

35 23. In a telephone system, subscribers' lines, trunk lines, means for establishing and maintaining a plurality of trunk connections between a plurality of said trunk lines and one of said subscribers' lines, means for holding and guarding said trunk connections while establishing a local connection between said subscriber's line and another local subscriber's line, means for transferring either trunk connection to said other subscriber's line, and means for transmitting a tone to said first subscriber to indicate the transfer of said trunk connection to said other subscriber's line.

24. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for guarding said trunk connection to prevent all subscribers' lines except said second line from completing connection with said trunk connection. 70

75 25. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for guarding said trunk connection to prevent all subscribers' lines except said second line from completing connection with said trunk connection. 80

85 90 26. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for transmitting a tone to said first line to indicate the transfer of said trunk connection to said second line. 95

100 105 27. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for guarding said trunk connection to prevent all subscribers' lines except said second line from completing connection with said trunk connection, and means for transmitting a tone to said first line to indicate the transfer of said trunk connection to said second line. 110

115 120 28. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for guarding said trunk connection to prevent all subscribers' lines except said second line from completing connection with said trunk connection, and means for transmitting a tone to said first line to indicate the transfer of said trunk connection to said second line. 125

120 29. In a telephone system, a local exchange and a main exchange, two-way trunk lines

connecting said exchanges, local subscribers' lines accessible to each other and to said trunk lines, means for establishing connections between said trunk lines and said subscribers' lines and locally between said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line locally calling said second line and said second line thereafter answering said trunk call, and means for transferring a second trunk connection while holding a first trunk connection.

28. In a telephone system, a local exchange and a main exchange, two-way trunk lines connecting said exchanges, local subscribers' lines accessible to each other and to said trunk lines, means for establishing connections between said trunk lines and said subscribers' lines and locally between said subscribers' lines, subscriber-controlled means associated with each subscriber's line for holding an established trunk connection while completing other trunk and local connections, means for transferring a trunk connection from a first subscriber's line to a desired second subscriber's line in response to said first line calling said second line and said second line thereafter answering said trunk call, and means for permitting only one trunk connection at a time to be transferred.

29. In a telephone system wherein a plurality of subscribers' lines are each provided with an answering key for answering trunk calls incoming over a plurality of trunk lines connected with a distant exchange, means for holding a trunk call while a subscriber completes a local connection to another local subscriber's line, and means responsive to said other local subscriber operating his answer key for transferring said held trunk call from, 40 the first subscriber's line to the said other subscriber's line.

30. In a telephone system wherein a plurality of subscribers' lines are each provided with an answering key for answering trunk calls incoming over a plurality of trunk lines connected with a distant exchange, means for holding a trunk call while a subscriber completes a local connection to another local subscriber's line, means responsive to said other local subscriber operating his answer key for transferring said held trunk call from the first subscriber's line to the said other subscriber's line, and means for guarding said held connection to prevent all subscribers 50 except said other subscriber from completing connection with said held trunk call in response to the operation of their answer keys.

31. In a telephone system wherein a plurality of subscribers' lines are each provided with an answering key for answering trunk

calls incoming over a plurality of trunk lines connected with a distant exchange, means for holding a trunk call while a subscriber completes a local connection to another local subscriber's line, means responsive to said other local subscriber operating his answer key for transferring said held trunk call from the first subscriber's line to the said other subscriber's line, means for guarding said held connection to prevent all subscribers except said other subscriber from completing connection with said held trunk call in response to the operation of their answer keys, and means for transmitting a tone to said first subscriber in response to the transfer of said call.

32. In a telephone system wherein a plurality of subscribers' lines are each provided with an answering key for answering trunk calls incoming over a plurality of trunk lines connected with a distant exchange, a step-by-step finder associated with each trunk line, means responsive to the operation of an answer key by any subscriber in response to an incoming trunk call for operating the finder associated with the trunk line having the incoming call to hunt for and connect the subscriber's line associated with the operated key with said trunk line, means for holding said trunk call while said subscriber completes a local connection to another subscriber's line in case said other subscriber is desired for the trunk call, and means responsive to said other subscriber operating his answer key for reoperating said trunk finder to hunt for and connect said trunk line to 100 said other subscriber's line.

33. In a telephone system, subscribers' lines, a code-call switch, means for establishing a connection between one of said lines and said switch, means responsive to said connection for operating said switch to connect with said calling line, means for automatically releasing said first established connection responsive to said last connection, means for operating said switch to signal a called subscriber, and means responsive to the called subscriber answering for completing a connection between the calling and called subscribers, said connection including said code-call switch.

34. In a telephone system, subscribers' lines, a code-call finder, a finder-connector link, means responsive to the initiation of a call by one of said subscribers for operating the finder of the finder-connector link to find and connect with the calling line, means for operating the connector of the finder-connector link to connect with said code-call finder, means responsive to said connection for operating said code-call finder to find and connect with said calling line, and means for automatically releasing said finder-connector link responsive to said last connection.

35. In a telephone system, subscribers' lines, a code-call finder, a finder-connector

link, means responsive to the initiation of a call by one of said subscribers for operating the finder of the finder-connector link to find and connect with the calling line, means for operating the connector of the finder-connector link to connect with said code-call finder, means responsive to said connection for operating said code-call finder to find and connect with said calling line, means for automatically releasing said finder-connector link responsive to said last connection, code-call signals, and means controlled by said subscriber for operating said code-call finder to operate said signals.

36. In a telephone system, subscribers' lines, a code-call finder, a finder-connector link, means responsive to the initiation of a call by one of said subscribers for operating the finder of the finder-connector link to find and connect with the calling line, means for operating the connector of the finder-connector link to connect with said code-call finder, means responsive to said connection for marking the calling line in the banks of the code-call finder by way of the banks of the finder in the finder-connector link, means responsive to said connection for operating the code-call finder to find said marked condition and connect the code-call finder to the calling line, and means responsive to said last connection for automatically releasing said finder-connector link.

37. In a telephone system, subscribers' lines, two-way trunk lines, a step-by-step finder individual to each trunk line, subscriber-controlled means for initiating the operation of a finder to find the subscriber's line in response to answering an incoming trunk call or in response to originating an outgoing trunk call, and means for restricting some of said subscribers from making outgoing trunk calls by preventing the operation of a finder in response to the operation of said subscriber controlled means when an attempt is made to originate an outgoing trunk call.

38. In a telephone system, a local exchange, a plurality of subscribers' lines at said local exchange, a main exchange, a plurality of trunk lines connecting said exchanges, a key individual to each subscriber's line, each of said keys being common to all said trunk lines, and means operated responsive to the operation of any one of said keys for connecting any one of said trunk lines to the subscriber's line associated with the operated key.

39. In a telephone system wherein a trunk finder terminating a trunk line is operated to complete incoming and outgoing calls for local subscribers' lines, two test wipers and a single test circuit in said finder, the first of said wipers normally connected to said test circuit and effective for completing outgoing calls responsive to the operation of said finder, and means for disconnecting said

first wiper from said test circuit and for connecting the second wiper to said test circuit to complete incoming calls responsive to the operation of said finder.

40. In a telephone system where a trunk finder terminating a trunk line is operated to complete incoming, outgoing, and transfer calls for local subscribers' lines, three test wipers and a single test circuit in said finder, the first of said wipers normally connected to said test circuit and effective for completing outgoing calls responsive to the operation of said finder, means for connecting the second of said wipers to said test circuit to complete incoming calls responsive to the operation of said finder, and means for connecting the third wiper to said test circuit to complete transfer calls responsive to the operation of said finder.

41. In a single level switch, wipers, means for operating the wipers of said switch in only a single directive movement to complete a connection in response to the receipt of a certain number of impulses, means for operating the wipers of said switch in only two directive movements to complete a connection in response to the receipt of a predetermined first digit and a variable second digit, and means for operating the wipers of said switch in a first directive movement, an automatic stepping movement and then a further directive movement to complete a connection in response to the receipt of a different predetermined digit and a variable second digit.

42. In a telephone system, a plurality of subscribers' lines, a talking circuit common to all said lines, a calling device individual to each line for transmitting a long or a short series of impulses over said common talking circuit dependent upon the value of the digit dialled on each operation thereof, and a plurality of signals common to all said lines and operated once for each transmitted series of impulses to code ring a desired subscriber by a combination of long and short rings in response to the operation of said calling device.

I, witness whereof, I hereunto subscribe my name this 8th day of May, A. D. 1931.

JOHN H. VOSS.
